UNITED STATES PATENT OFFICE.

CHARLES E. GIERDING, OF NEWARK, NEW JERSEY.

FARE-REGISTER.

No. 892,986.

Specification of Letters Patent.

Patented July 14, 1908.

Application filed July 25, 1907. Serial No. 385,525.

To all whom it may concern:

Be it known that I, CHARLES E. GIERDING, a citizen of the United States of America, and a resident of Newark, in the State of New Jersey, have invented a new and useful Improvement in Fare-Registers, of which the following is a specification.

This invention relates primarily to what are known in the art as "double" fare registers; that is to say, fare registers adapted for the registration separately of cash fares and transfers, or any other two kinds of fares, and for the indication at all times of the kind of fare last registered. The invention may, however, in part be embodied in fare registers or recorders or combined registers and recorders, hereinafter referred to in common as fare registers, and also in part in registers or recorders or combined registers and recorders other than fare registers. These latter are herein referred to, in common with fare registers, as "registers".

The present improvement as a whole is confined to those fare registers or other registers in which decimal numeral wheels are employed in a trip register, or its equivalent, at least, and preferably in a permanent register or totalizer also, the axes of both sets of wheels being in that case conveniently parallel with each other.

The invention consists in certain novel combinations of parts hereinafter described and claimed. These combinations have been and are preferably embodied in an improved double fare register, which will be shown as a whole and briefly described to set forth the intended and preferred setting of the present invention.

The leading object of the present invention is to prevent overmovements of the numeral wheels in the registering and resetting operations respectively by means of devices having other essential functions of importance, and thus to simplify the improved register and adapt the same to resist the severe strains to which fare registers especially are subjected in use.

Other objects of the invention are to provide for locking the respective actuation transmitters of the specific improved double register during the resetting operation; to facilitate assembling and separating the parts especially with reference to attaching and detaching the left-hand actuation indicator of a double register; and to provide

for actuating a double fare indicator or the like and for holding the same steadily in its respective positions by mechanical devices of superior simplicity and strength.

Other objects will be set forth in the general description which follows.

Six sheets of drawings accompany this specification as part thereof.

Figures 1, 2 and 3 are respectively a face view, an edge view and a back view of a double fare register embodying the present improvement as a whole; Fig. 4 is a face view of the same on a larger scale with the front part of the casing drum and the dial removed; Figs. 5 and 6 are detail end views of the main shaft, showing the left-hand side of two of the trip-register numeral wheels and illustrating respectively the registering operation and the resetting operation; Fig. 7 is a perspective view of the left-hand actuation indicator detached; Fig. 8 is a face view confined to the back part of the register drum and the parts attached to its back plate; Fig. 9 is a perspective view of the left-hand transmission slide; Figs. 10 and 11 are sectional edge views of the partly dismantled register as shown in Fig. 4, from its left-hand side, illustrating the registering operation; Fig. 12 is a fragmentary sectional face view illustrating the transmission of registrations to the trip-register and totalizer numeral wheels; Figs. 13 and 14 are sectional side views of the partly dismantled register as shown in Fig. 4, from the right-hand side; Fig. 15 is a sectional detail of certain parts of the actuating mechanism hereinafter more particularly described; Fig. 16 represents a cross section through the fare indicator and its rock shaft; Figs. 17 and 18 are perspective views of the respective locking bolts detached; Figs. 19 and 20 are front views of the upper part of the works of the improved register, with the left-hand actuation indicator, the direction indicator and other parts omitted, more clearly illustrating the construction and operation of the parts for locking the actuation transmitters and for preventing overmovements in the resetting operation; and Fig. 21 is a fragmentary section on the line A—B, Fig. 20.

Like reference characters refer to like parts in all the figures.

The external characteristics of the specific register represented by the drawings include a round case having sheet-metal drum parts,

1 and 2, suitably connected with each other, and a circular dial plate, 3, exposed to view as in Fig. 1, through the customary front plate of glass. This dial plate has seven index openings, or sight-holes, two of which, *a* and *b*, expose to view the numerals on the respective sets of trip-register numeral wheels, *c* and *c'*, and the respective actuation indicators, *d* and *d'*, Fig. 4, etc.; another pair, 10 *a*² and *b*², expose to view the numerals on the respective sets of totalizer numeral wheels, *e* and *e'*; the third pair, *a*³ and *b*³, the respective signs of the fare indicator, *f*, and the seventh opening, *a*⁴, the respective signs of the direction indicator, *g*. All the descriptive signs are disappearing; only those that are for the time being correct are exposed to view.

The back of the register case is formed by 20 a substantially flat cast-iron back plate, 4, (Fig. 3, etc.) having hanging lugs, *h* and *h'*, to interact with the customary staples of a suitable operating back (not shown) which for the purposes of the present invention may be 25 of the construction set forth in my specification forming part of United States Letters Patent No. 800566, dated September 26, 1905, or of any known or improved construction.

30 A pair of vertically movable actuation studs, 5 and 5', protrude through slots, *i* and *j*, Fig. 3, in the back plate 4 to interact with the pulling devices within the operating back, in customary manner; and the customary resetting knob, *k*, protrudes at the right-hand side of the register case. Said actuation studs 5 and 5' project from the backs of a pair of actuation slides, *l* and *l'*, guided on the face of the back plate 4, as in 35 Fig. 8, and normally held in the retracted position in which they are shown in Fig. 8 by tensile springs, *m* and *m'*, stretched between studs, 6 and 7, on the slides and on the back plate 4, respectively.

40 45 Complete strokes of the actuation slides *l* and *l'* are insured in customary manner by a pair of dogs, *n* and *n'*, Fig. 8, pivoted on the face of the back plate 4, interacting with ratchet racks, 8 and 8', formed on the inner 50 edges of the respective slides, and owing to this arrangement a central double-acting spring, *o*, connected with the respective dogs, serves to hold both dogs in the normal position of rest in which they are shown in 55 Fig. 8. The dogs *n* and *n'* and their pivotal supports, together with the interacting portions of the spring *o*, are preferably and conveniently guarded by a sheet metal shield, *p*, Fig. 8, against obstruction by oil thrown off 60 by the mechanism in front of them. The pulling of both slides, *l* and *l'*, simultaneously is prevented in customary manner by means of a central laterally swinging stop, *q*, Fig. 8, interacting with shoulders, 9 and 9', 65 on the respective slides.

Concentric bells, *r* and *r'*, Fig. 8, of different tones, are conveniently attached to the back plate 4 by a central post, 10, common to both, which also forms the pivot of the stop *q*, and the bell hammers, *s* and *s'*, and their 70 striking springs, *t* and *t'*, are also conveniently and preferably attached to the back plate 4, as shown in the same figure. The respective bell hammers have tripping levers, *u* and *u'*, suitably connected therewith and 75 projecting in the path of trip studs, 11 and 11', on the respective slides. This bell mechanism forms no part of the present invention, but is briefly described as a part of the 80 double fare register represented by the drawings. The respective actuation slides *l* and *l'* are further provided, respectively, with forwardly projecting pairs of transmission lugs, 12 and 12', at their outer edges, and the left-hand slide *l*, shown detached by Fig. 9, has 85 in addition a like pair of lugs, 13, only smaller as shown, carried by a projection from the inner edge of the slide. Each slide carries also a buffer, 14, at its upper end, to contact with a matching stop, *v*, on the back plate 4. Said transmission lugs, 12 and 12', of the actuation slides *l* and *l'* interact with 90 crank pins, 15 and 15', forming parts of a pair of rocking actuation transmitters, as they are herein termed, which are shown at 95 *w* and *w'* in Figs. 4, etc., and are pivoted on a main horizontal shaft, *x*, common to both of the two sets of registering mechanism, which are mounted side by side on the back plate 4 as shown in Fig. 4; said shaft and the 100 remainder of the two sets of mechanism being supported by one pair of frame pieces, *y* and *z*, rigidly attached to the back plate by two pairs of screws, 16, 17 and 18, 19, one screw of each pair being inserted from outside, as 105 shown in Fig. 3. By removing these screws the whole of both sets of the registering mechanism apart from the elements attached to the back plate, as in Fig. 8, may be quickly detached when it is necessary to 110 repair or replace any part, and the original assembling of the mechanism is also materially facilitated. A pair of horizontal countershafts, *x*² and *x*³, in line with each other, are supported next beneath said main shaft 115 *x*; and horizontal totalizer shafts *x*⁴ and *x*⁵, are supported between said frame pieces, *y* and *z*, at bottom; with the aid of a central support, 20, Figs. 4, 10 and 12, for the inner ends of the countershafts *x*² and *x*³, sustained 120 in position by two horizontal tie rods, 21 and 22. A central link, 23, Figs. 4, 10 and 12, connects the totalizer shaft *x*⁵ with the lowermost of two horizontal sub-shafts, *x*⁶ and *x*⁷, supported by the frame pieces, *y* and *z*, 125 above the trip-register wheels *c* and *c'*, and below the totalizer wheels *e* and *e'*, respectively. Said main shaft *x* supports the two sets of trip-register numeral wheels *c* and *c'* and said totalizer shafts *x*⁴ and *x*⁵ support the 130

5 numeral wheels e and e' of the respective totalizers. All the trip-register numeral wheels c and c' are loose on said main shaft x , and are connected with each other by spur-
5 gear transfer mechanism hereinafter more particularly described, the respective parts of which are shown at 24, 25 and 26 in Figs. 4, 5 and 19-21. The left-hand units wheel of the totalizer wheels e and e' is preferably
10 fast on the totalizer shaft x^4 , Fig. 12, the same being a sleeve shaft; the other totalizer wheels are loose on the respective totalizer shafts x^4 and x^5 , and motion is transferred from wheel to wheel in substantially
15 the same manner as in the trip register. The transfer pinions represented at 25 and like transfer pinions, 25^x, Figs. 4, etc., forming part of the totalizer transfer mechanism, are loose on said sub-shafts, x^6 and x^7 , respectively.

20 The actuation transmitters w and w' , being concentric with the trip-register numeral wheels c and c' , the right-hand transmitter w' conveniently carries the actuation indicator d' of the adjacent trip-register numeral wheels c' . In order to provide for the employment of a left-hand actuation indicator d in the form of a "blind" confined to the units and tens wheels of the left-hand wheels c as shown, or it may be to the units wheel alone, the left-hand indicator d is carried by a central rocking support, w^2 , as shown detached in Fig. 7; a crank pin, 27, at the rear end of said support interacting with said transmission lugs 13 at the inner edge of the left-hand actuation slide l . To facilitate pivoting this indicator support on the main shaft x , and attaching and detaching the same in assembling and repairing the mechanism, the support w^2 is constructed with an open bearing, 28, Fig. 7, closed by a swinging cap piece, 29, which is locked in its closed position by means of a screw, 30, interacting with a pair of lugs formed respectively on the body of 45 the support and on said cap piece. Each of the actuation transmitters w and w' is further constructed with a transmission notch, 31, Fig. 14, at a suitable peripheral point, and with peripheral locking surfaces, 32 and 50 33, on both sides of such notch, concentric with the main shaft. Contiguous to this portion of each of the actuation transmitters a pair of combined ratchet wheels and star pinions, 34, are fast on the respective countershafts x^2 and x^3 . A spring-pressed working pawl, a' , Fig. 15, carried by each actuation transmitter interacts with the ratchet notches, 35, of the combined ratchet wheel and star pinion 34 adjacent thereto, and a 55 spring-pressed detent pawl, b' , interacts therewith at another point; the respective detent pawls being supported by the respective frame pieces y and z , as in Figs. 10 and 11 and Figs. 13 and 14.

60 65 The star teeth, 35^x, Fig. 14, of each of the

combined ratchet wheels and star pinions 34, interact with the locking surfaces 32 and 33 of the actuation transmitters w and w' before and after each actuation, as in Fig. 14, and during each act of transmission interact with 70 the notches 31 of the respective actuation transmitters; the interaction first named serving to prevent overmovements of the actuation transmitters and the parts movable therewith in a highly effective manner. 75

Rotation is transmitted from each of the respective countershafts x^2 and x^3 by two trains, 36 and 37 or 36' and 37', of spur gearing, as in Fig. 12. The first of said trains of spur gearing, shown at 36 or 36', transmits 80 rotation to the units wheel of the corresponding set of trip-register numeral wheels c or c' , and the other train, 37 or 37', transmits rotation simultaneously to the units wheel of the corresponding totalizer wheels e or e' . 85 The units wheels of all the several sets of numeral wheels are thus positively geared to said countershafts x^2 and x^3 , and controlled in common therewith; and said spur-gear transfer mechanism (24, 25, 26) of the respective 90 sets of wheels connects them in like manner with the respective countershafts, so that all the numeral wheels are brought under the same control as to overmovements in the registering operation. Each of the spur-gear trains 37 and 37' includes an idle wheel 37^x supported by the contiguous side piece y or z .

95 The fare indicator f , Figs. 1, 4 and 16, is common to the two trains of registering 100 mechanism, having two faces appropriate to the respective trains and bearing in line with them respectively the signs "Cash fares" and "Transfers", or as the case may be. The indicator f oscillates on the axis of a horizontal rock shaft, 38, and exposes the appropriate sign when a fare of that description is first registered for the time being, and as long as fares of the same kind are registered, and is reversed to expose the other sign when a 110 fare of the other kind is registered. It is moved into its respective positions by a pair of sliding pitmen, 39 and 39', Figs. 4, 10, 11, 13 and 14, pivoted to the respective actuation transmitters w and w' at their upper 115 ends, and provided at their lower ends with guide slots, 40 and 40', through which the rock shaft 38 extends, and with lugs, 41 and 41', which come into contact with tappet arms, 42 and 42', fast on the respective ends 120 of the rock shaft.

125 The tappet arms 42 and 42' are shown in Figs. 10 and 14 and in full lines in Fig. 13 in the position corresponding with the sign "Transfer" in Figs. 1 and 4. When a cash fare is next registered the lug 41', Figs. 13 and 14, of the sliding pitman 39' connected with the right-hand actuation transmitter w' comes in contact with the tappet arm 42', and turns the same downward as in dotted 130

lines in Fig. 13, and the sign Cash is then exposed to view. The operation of the fare indicator *f* is further illustrated by Figs. 10 and 11, which see. When the right-hand tappet arm 42' is in said dotted downturned position (Fig. 13) the left-hand tappet arm 42 projects rearward as in Fig. 10, and when the left-hand registering train is again actuated as in Fig. 11, the left-hand tappet arm 42 is turned downward as in this figure, and the right-hand tappet arm 42' is turned forward into the path of the corresponding tappet lug 41', as in Fig. 14 and in full lines in Fig. 13. The fare indicator *f* is held in its respective positions of rest by a tensile spring, 43, Figs. 10 and 11, interacting with a dog, 44, having a V-shaped face which contacts with the respective sides of a V-shaped projection, 45, on the hub of the left-hand tappet arm 42 as shown in these figures respectively; said spring 43 being stretched from a stud pin, 46, on the contiguous side of the left-hand frame piece *y*.

The outer ends of the main shaft *x* and countershafts *x*² and *x*³ are supported by bridge pieces, *y*² and *z*², fixedly attached to the outer sides of the respective frame pieces *y* and *z*, and the right-hand bridge-piece *z*² is provided with the customary locking lug, 47, Figs. 4, 13, 19 and 20, interacting with a notched collar, 48, fast on the main shaft *x*, to render the main shaft *x* normally non-rotary, and also to interact with the inner face of said collar 48 to lock said shaft *x* in its resetting position (Fig. 20); the shaft *x* being movable endwise, by means of the resetting knob *k*, to unlock it for rotation, and to bring the resetting devices within the several trip-register numeral wheels *c* and *c'* into contact relation with each other. These devices are, or may be, of the description set forth in my specification forming part of United States Letters Patent No. 800565, dated September 26, 1905, and are exposed to view in Figs. 5 and 6, which see; the same including rigid studs, 49, on the main shaft *x*, which during the registering operation are located to the left of the respective trip-register numeral wheels *c* and *c'*.

As each fare is rung up on one or the other of the bells *r* or *r'* it is simultaneously registered by the trip-register numeral wheels *c* or *c'* of the appropriate registering train, and simultaneously by the corresponding totalizer wheels *e* or *e'*, as already indicated. In this operation the trip-register units wheel receives its motion from the adjoining spur wheel of the gearing 36 or 36' through the medium of a clutch wheel, 50, Figs. 5 and 6, fixedly attached to such spur wheel, and clutched to the numeral wheel in the manner illustrated by Fig. 5. A tumbler, 51, pivoted to the web of the numeral wheel and acted on by a tensile spring, 52, stretched to a relatively fixed stud within the numeral

wheel, carries a stud, 53, which interlocks with one of the peripheral notches of the clutch wheel 50 during the registering operation, as in Fig. 5.

Motion is transmitted or transferred in the registering operation from one numeral wheel to the next wheel to the left throughout the register as aforesaid by spur-gear transfer mechanism represented at 24, 25 and 26. In the case of the trip-register wheels *c* and *c'* this includes "transmission attachments" 24 herein termed transfer lugs, each, as shown in Fig. 5, in the form of a pair of spur teeth united with each other at their inner ends, the interdental notch corresponding with the customary peripheral notch of the transfer mechanism; such transfer lugs adapting the transfer mechanism to be utilized as zero stops in the resetting operation as set forth and claimed in a previous specification forming part of United States Letters Patent No. 841084, dated January 8, 1907.

In the registering operation, when the notch of each of the lugs 24 is not occupied by one of the star-wheel teeth of the adjoining pinion 25, two of said star-wheel teeth contact with the periphery of the customary transfer ring, 24^X, Fig. 5, which carries the lug 24, to prevent idle movements of the pinion and of the numeral wheel geared thereto by the adjoining gear 26.

When the main shaft *x* is pulled preliminary to the resetting operation, the stud 49, Figs. 5 and 6, at the left of each trip-register numeral wheel *c* or *c'*, is moved into the plane of the corresponding clutch tumbler 51, and in the resetting operation which follows said stud interacts with the notched inner end of the tumbler, as in Fig. 6; serving first to unclutch the numeral wheel from the corresponding spur wheel, and then to transmit backward rotation from the shaft *x* to the numeral wheel; such resetting rotation being limited to the backward direction by a spring-pressed dog, 54, Figs. 5 and 6, within the numeral wheel interacting with the notches of the clutch wheel, 50, as well as by the customary spring-pressed dog, 55, Fig. 13, etc., interacting with peripheral notches in the shaft locking collar 48, Figs. 4, 13, etc., adjacent to the resetting knob *k*. When the main shaft *x* is so pulled by the knob *k*, motion is furthermore transmitted therefrom by means of a lever, 56, Figs. 4, 13, etc., at the right-hand side of the register, interacting with said locking collar 48, and carrying near the top of the register one of a pair of locking bolts, 57 and 57', shown detached by Figs. 17 and 18, respectively, which interlock with peripheral projections, 58 and 58', on the respective actuation transmitters *w* and *w'* in the resetting position of the main shaft, as in Fig. 20, and have notches, 59 and 59', to clear said projections in the registering position.

tion of the main shaft, as in Figs. 4 and 19. Said locking bolts 57 and 57' are connected with each other and with a retracting spring, 60, Figs. 10, etc., which also serves to hold the main shaft x in its registering position, by a horizontal slide, 61, best shown in Figs. 19, 20, and 21, which see. Said slide 61 is guided by sleeve portions, 62, embracing a horizontal tie rod, 62^x, at the top of the register, and interacts with the respective bolts 57 and 57' by means of rigidly depending fingers, 63 and 63', at the respective ends of the slide. The retracting spring 60 is stretched from a pin, 64, at the right-hand end of the slide 61 to the left-hand frame piece y , to which it is conveniently attached as shown in Figs. 10 and 11.

The lower edge of the slide 61 is constructed with rigid tooth-like projections, 65, which in the resetting position of the main shaft x and slide 61 (Fig. 20) interlock positively with the teeth of the trip-register transfer pinions 25 and thus adapt these pinions to interact with said transfer lugs 24 carried by the units and tens wheels of the trip-register numeral wheels c and c' as means for preventing overmovements of these wheels in the resetting operation. The slide 61 is also provided with depending rigid projections, 66, which contact with the shaft x^6 , as best shown in Fig. 21, to relieve the slide from torsional strain when the lugs 24 contact with the locked pinions 25 at the end of each resetting operation.

35 The hundreds wheel of each set of the trip-register wheels c and c' is prevented from being turned backward beyond zero in the resetting operation by a spring-pressed dog 67 or 67' pivoted on said shaft x^6 which supports the transfer pinions 25, and interacting with a peripherally notched disk 68 or 68', as heretofore. Compare Fig. 6 and Fig. 20.

The direction indicator g , Figs. 1 and 4, is reversed during each resetting operation to indicate the succeeding trip by means represented as a whole in Fig. 10, which see. The main shaft x is provided inside the left-hand frame piece y with a pinion, 69, splined thereto and connected by an idle wheel, 70, with a spur wheel, 71, of twice its diameter, carrying a crank pin, 72, and the latter is connected by a pitman, 73, with a crank arm, 74, fast on the left-hand end of a rock shaft, 75, which carries the direction indicator.

55 Suitably apertured sheet-metal frame pieces, 76 and 77, Figs. 4, etc., frame the individual numerals of the trip-register wheels c and c' , and the totalizer wheels, e and e' , respectively, behind the sight holes a , b , a^2 and b^2 in the dial plate 3 in customary manner.

It will be understood that devices and details of construction not essential to the respective combinations of parts hereinafter

claimed may be omitted or changed at will; 65 and other like modifications will suggest themselves to those skilled in the art.

Having thus described said improvement, I claim as my invention and desire to patent under this specification:

1. The combination, in a register, of a rocking actuation transmitter constructed with a peripheral notch and a concentric peripheral locking surface adjoining said notch, a working pawl carried by said transmitter, 75 a combined ratchet wheel and star pinion interacting with said pawl and with said notch and locking surface, a countershaft upon which said combined ratchet wheel and pinion is mounted, gearing transmitting rotation from said countershaft, and a set of numeral wheels to the units wheel of which motion is transmitted by said gearing.

2. The combination, in a register, of a rocking actuation transmitter constructed 85 with a peripheral notch and a concentric peripheral locking surface adjoining said notch, a working pawl carried by said transmitter, a combined ratchet wheel and star pinion interacting with said pawl and with said notch 90 and locking surface, a countershaft upon which said combined ratchet wheel and pinion is mounted, gearing transmitting rotation from said countershaft, a set of numeral wheels to the units wheel of which motion is 95 transmitted by said gearing, and a totalizer simultaneously actuated by said gearing.

3. The combination, in a register, of a rocking actuation transmitter constructed with a peripheral notch and a concentric 100 locking surface adjoining said notch, a working pawl carried by said transmitter, a combined ratchet wheel and star pinion interacting with said pawl and with said notch and locking surface, horizontal numeral- 105 wheel shafts and a countershaft parallel therewith, the latter rotated by said combined ratchet wheel and pinion, gearing transmitting rotation from said countershaft, and a set of numeral wheels mounted 110 on each of said numeral-wheel shafts and to the units wheels of which motion is transmitted by said gearing.

4. The combination, in a register, of a rocking actuation transmitter constructed 115 with a peripheral notch and a concentric peripheral locking surface adjoining said notch, a working pawl carried by said transmitter, a combined ratchet wheel and star pinion interacting with said pawl and with said notch 120 and locking surface, a horizontal main shaft and a horizontal countershaft upon which said transmitter and said combined ratchet wheel and pinion respectively are mounted, gearing transmitting rotation from said 125 countershaft, a set of numeral wheels mounted on said main shaft and to the units wheel of which motion is transmitted by said gear-

ing, and spur-gear transfer mechanism for transmitting motion from wheel to wheel in the registering operation.

5. The combination, in a register, of a 5 rocking actuation transmitter constructed with a peripheral notch and a concentric peripheral locking surface adjoining said notch, a working pawl carried by said transmitter, a combined ratchet wheel and star pinion interacting with said pawl and with said notch and locking surface, a horizontal main shaft and a horizontal countershaft upon which said transmitter and said combined ratchet wheel and pinion respectively are mounted, 10 gearing transmitting rotation from said countershaft, a set of numeral wheels mounted on said main shaft and to the units wheel of which motion is transmitted by said gearing, spur-gear transfer mechanism for transmitting motion from wheel to wheel in the 15 registering operation, and a totalizer simultaneously actuated by said gearing.

6. The combination, in a register, of a 20 rocking actuation transmitter constructed with a peripheral notch and a concentric peripheral locking surface adjoining said notch, a working pawl carried by said transmitter, a combined ratchet wheel and star pinion interacting with said pawl and with said 25 notch and locking surface, horizontal numeral-wheel shafts and a countershaft parallel therewith, the latter rotated by said combined ratchet wheel and pinion, gearing transmitting rotation from said countershaft, spur-gear transfer mechanism for 30 transmitting motion from wheel to wheel in the registering operation, and a set of numeral wheels mounted on each of said numeral-wheel shafts and to which motion is 35 transmitted by said gearing.

7. The combination, in a register, of a 40 rocking actuation transmitter constructed with a peripheral notch and a pair of concentric peripheral locking surfaces adjoining the 45 respective sides of said notch, a working pawl carried by said transmitter, a combined ratchet wheel and star pinion interacting with said pawl and with said notch and locking surfaces, a countershaft upon which 50 said combined ratchet wheel and pinion is mounted, gearing transmitting rotation from said countershaft, and a set of numeral wheels mounted on said main shaft and to the units wheel of which motion is transmitted by said gearing.

8. The combination, in a register, of a 55 rocking actuation transmitter constructed with a peripheral notch and a pair of concentric peripheral locking surfaces adjoining the 60 respective sides of said notch, a working pawl carried by said transmitter, a combined ratchet wheel and star pinion interacting with said pawl and with said notch and locking surfaces, a countershaft upon which said 65 combined ratchet wheel and pinion is mount-

ed, gearing transmitting rotation from said countershaft, a set of numeral wheels mounted on said main shaft and to the units wheel of which motion is transmitted by said gearing, and a totalizer simultaneously actuated 70 by said gearing.

9. The combination, in a register, of a 75 rocking actuation transmitter constructed with a peripheral notch and a pair of concentric peripheral locking surfaces adjoining the 80 respective sides of said notch, a working pawl carried by said transmitter, a combined ratchet wheel and star pinion interacting with said pawl and with said notch and locking surfaces, horizontal numeral-wheel shafts and a countershaft parallel therewith, the latter rotated by said combined ratchet wheel and pinion, gearing transmitting rotation from said countershaft, and a set of numeral wheels mounted on each 85 of said numeral-wheel shafts and to the units wheel of which motion is transmitted by said gearing.

10. The combination, in a register, of a 90 back plate, a pair of frame pieces perpendicular to said back plate and rigidly attached thereto, an actuation slide movable vertically upon said back plate, means for pulling and retracting said slide, a rocking actuation transmitter interacting with said slide and constructed with a peripheral notch and a 95 concentric peripheral locking surface adjoining said notch, a working pawl carried by said transmitter, a combined ratchet wheel and star pinion interacting with said pawl and with said notch and locking surface, a horizontal main shaft and a horizontal countershaft mounted in said frame pieces and upon which said transmitter and said combined ratchet wheel and star pinion respectively are mounted, gearing transmitting rotation from said countershaft, and a set of 100 numeral wheels mounted on said main shaft to the units wheel of which motion is transmitted by said gearing.

11. The combination, in a register, of a 105 back plate, a pair of frame pieces perpendicular to said back plate and rigidly attached thereto, an actuation slide movable vertically upon said back plate, means for pulling and retracting said slide, a rocking actuation transmitter interacting with said slide and constructed with a peripheral notch and a concentric peripheral locking surface adjoining said notch, a working pawl carried by 110 said transmitter, a combined ratchet wheel and star pinion interacting with said pawl and with said notch and locking surface, a horizontal main shaft and a horizontal countershaft mounted in said frame pieces and upon which said transmitter and said combined ratchet wheel and pinion respectively are mounted, gearing transmitting rotation from said countershaft, a set of 115 numeral wheels mounted on said main shaft to the units wheel of which motion is transmitted by said gearing.

units wheel of which motion is transmitted by said gearing, and a totalizer simultaneously actuated by said gearing.

12. The combination, in a register, of a back plate, a pair of frame pieces perpendicular to said back plate and rigidly attached thereto, an actuation slide movable vertically upon said back plate, means for pulling and retracting said slide, a rocking actuation transmitter interacting with said slide and constructed with a peripheral notch and a concentric peripheral locking surface adjoining said notch, a working pawl carried by said transmitter, a combined ratchet wheel and star pinion interacting with said pawl and with said notch and locking surface, horizontal numeral-wheel shafts and a countershaft parallel therewith, the latter rotated by said combined ratchet wheel and pinion, gearing transmitting rotation from said countershaft, and a set of numeral wheels mounted on each of said numeral-wheel shafts and to the units wheel of which motion is transmitted by said gear-
ing.

13. The combination, in a register, of a back plate, a pair of frame pieces perpendicular to said back plate and rigidly attached thereto, an actuation slide movable vertically upon said back plate, means for pulling and retracting said slide, a rocking actuation transmitter interacting with said slide and constructed with a peripheral notch and a concentric peripheral locking surface adjoining said notch, a working pawl carried by said transmitter, a combined ratchet wheel and star pinion interacting with said pawl and with said notch and locking surface, a horizontal main shaft and a horizontal countershaft mounted in said frame pieces and upon which said transmitter and said combined ratchet wheel and pinion respectively are mounted, a spring-pressed detent pawl in mesh with said ratchet wheel and supported by the adjoining frame piece, gearing transmitting rotation from said countershaft, and a set of numeral wheels mounted on said main shaft to the units wheel of which motion is transmitted by said gear-
ing.

14. A double register having, in combination, a back plate common to all, a pair of frame pieces perpendicular to said back plate and rigidly attached thereto, a pair of vertically movable actuation slides supported on said back plate between said frame pieces, a pair of rocking actuation transmitters interacting with the respective slides, a pair of horizontal countershafts which receive intermittent rotation from the respective transmitters, means whereby each countershaft is locked against overmovement at the end of each registering actuation, spur gearing transmitting rotation from the respective countershafts, and two sets of numeral

wheels mounted in horizontal series between said frame pieces, the units wheel of each set being rotated by the appropriate gearing in the registering operation.

15. A double register having, in combination, a back plate common to all, a pair of frame pieces perpendicular to said back plate and rigidly attached thereto, a pair of vertically movable actuation slides supported on said back plate between said frame pieces, a pair of rocking actuation transmitters interacting with said slides respectively, a pair of horizontal countershafts which receive intermittent rotation from said transmitters respectively, means whereby each countershaft is locked against overmovement at the end of each registering actuation, spur gearing transmitting rotation from the respective countershafts, two sets of numeral wheels mounted in horizontal series between said frame pieces, the units wheel of each set being rotated by said gearing in the registering operation, and spur-gear transfer mechanism for transmitting motion from wheel to wheel in the registering operation.

16. A double register having, in combination, a back plate, a pair of frame pieces perpendicular to said back plate and rigidly attached thereto, a pair of vertically movable actuation slides supported on said back plate, a pair of rocking actuation transmitters interacting with said slides respectively, a pair of horizontal countershafts in line with each other which receive intermittent rotation from said transmitters respectively and are mounted at their outer ends in said frame pieces, a pair of tie rods parallel with said countershafts, a central support for said countershafts, sustained by said tie rods, spur gearing transmitting rotation from said countershafts respectively, and two sets of numeral wheels mounted in horizontal series between said frame pieces, the units wheel of each set being rotated in the registering operation by said gearing.

17. A double register having, in combination, a back plate, a pair of frame pieces perpendicular to said back plate and rigidly attached thereto, a pair of vertically movable actuation slides supported on said back plate, a pair of rocking actuation transmitters interacting with said slides respectively, a pair of horizontal countershafts which receive intermittent rotation from said transmitters respectively, spur gearing transmitting rotation from said countershafts, two sets of numeral wheels supported in horizontal series between said frame pieces above said countershafts, the units wheel of each set being rotated in the registering operation by the appropriate gearing, and two sets of numeral wheels supported in horizontal series between said frame pieces beneath said countershafts, the units wheel of each set being simultaneously operated by the appro-
110

130

proper train of said gearing when the corresponding units wheel of the numeral wheels first named is actuated in the registering operation.

5 18. A double register having, in combination, a back plate, a pair of frame pieces perpendicular to said back plate and rigidly attached thereto, a pair of vertically movable actuation slides supported on said back
10 plate, a pair of rocking actuation transmitters, interacting with said slides respectively, a pair of horizontal countershafts in line with each other which receive intermittent rotation from said transmitters respectively, two
15 trains of spur gearing transmitting rotation from each of said shafts, two sets of numeral wheels supported in horizontal series between said frame pieces above said countershafts, the units wheel of each set being rotated in the registering operation by the appropriate train of said gearing, and two sets of numeral wheels supported in horizontal series between said frame pieces beneath said countershafts, the units wheel of each set being simultaneously operated by the appropriate train of said gearing when the corresponding units wheel of the numeral wheels first named is actuated in the registering operation.

30 19. A double register having, in combination, a back plate, a pair of frame pieces perpendicular to said back plate and rigidly attached thereto, a pair of vertically movable actuation slides supported on said back plate, a pair of rocking actuation transmitters interacting with said slides respectively, a pair of horizontal countershafts in line with each other which receive intermittent rotation from said transmitters respectively, two 35 trains of spur gearing transmitting rotation from each of said countershafts, two sets of numeral wheels supported in horizontal series between said frame pieces above said countershafts, the units wheel of each set being 40 rotated in the registering operation by the appropriate train of said gearing, two sets of numeral wheels supported in horizontal series between said frame pieces beneath said countershafts, the units wheel of each 45 set being simultaneously operated by the appropriate train of said gearing when the corresponding units wheel of the numeral wheels first named is actuated in the registering operation, the trains of gearing leading 50 to the subjacent numeral wheels including a left-hand train contiguous to the left-hand frame piece, and the units wheel of the left-hand set of said subjacent wheels having a 55 sleeve shaft by which it is connected with the 60 left-hand gearing.

20. A double register having, in combination, a back plate, a pair of frame pieces perpendicular to said back plate and rigidly attached thereto, a pair of vertically movable
65 actuation slides supported on said back

plate, a pair of rocking actuation transmitters interacting with said slides respectively, a pair of horizontal countershafts in line with each other which receive intermittent rotation from said slides respectively, two trains 70 of spur gearing transmitting rotation from each of said countershafts, two sets of numeral wheels supported in horizontal series between said frame pieces above said countershafts, the units wheel of each set being rotated in the registering operation by the appropriate train of said gearing, two sets of numeral wheels supported in horizontal series between said frame pieces beneath said countershafts, the units wheel of each 80 set being simultaneously operated by the appropriate train of said gearing when the corresponding units wheel of the numeral wheels first named is actuated in the registering operation, the trains of gearing leading to the subjacent numeral wheels including wheels supported by the respective frame pieces and the units wheel of the left-hand set of said subjacent wheels having a sleeve shaft by which it is connected with the left-hand gearing.

21. In a register, the combination with a set of numeral wheels and a horizontal shaft on which said wheels are loosely mounted, of means for actuating said wheels in the registering operation including a rocking actuation transmitter at the left-hand side of the wheels pivotally mounted on said shaft, an actuation indicator having a rocking support at the right-hand side of said wheels pivotally mounted on the same shaft and carrying a blind movable momentarily with the units wheel during the first part of each registering actuation and which does not extend to the left-hand wheel, and means for independently actuating said indicator. 95 105 130

22. In a register, the combination with a set of numeral wheels and a horizontal shaft on which said wheels are loosely mounted of means for actuating said wheels in the registering operation including an actuation slide movable vertically behind the same and a rocking actuation transmitter at the left-hand side of the wheels pivotally mounted on said shaft and interacting with said slide, and an actuation indicator having a rocking support at the right-hand side of the wheels pivotally mounted on the same shaft and interacting with the same slide, said support carrying a blind movable momentarily with the units wheel during the first part of each registering actuation and which does not extend to the left-hand wheel. 110 115 120

23. In a register, the combination with a set of numeral wheels and a horizontal shaft 125 on which said wheels are loosely mounted of means for actuating said wheels in the registering operation including an actuation slide movable vertically behind the same and a rocking actuation transmitter at the 130

left-hand side of the wheels pivotally mounted on said shaft and interacting with said slide, and at actuation indicator having a rocking support at the right-hand side of the wheels detachably pivoted on the same shaft and interacting with the same slide, said support carrying a blind movable momentarily with the units wheel during the first part of each registering actuation and which does not extend to the left-hand wheel.

24. In a double register, the combination with two sets of numeral wheels mounted side by side and a horizontal shaft on which said wheels are loosely mounted, of means for actuating said wheels in the registering operation including a pair of rocking actuation transmitters at the right-hand and left-hand sides of said wheels respectively pivotally mounted on said shaft, an actuation-indicator blind carried by the right-hand actuation transmitter, and an actuation indicator at the right-hand side of the left-hand set of wheels having a rocking support pivotally mounted on the same shaft, the indicator last named including a blind which in common with the blind first named is movable momentarily with the corresponding units wheel during the respective registering actuations, and which does not extend to the left-hand wheel.

25. In a double register, the combination with two sets of numeral wheels mounted side by side and a horizontal shaft on which said wheels are loosely mounted of means for actuating said wheels in the registering operation including a pair of actuation slides movable vertically behind said wheels and rocking actuation transmitters at the right-hand and left-hand sides of said wheels respectively pivotally mounted on said shaft and interacting with said slides respectively, an actuation indicator blind carried by the right-hand actuation transmitter, and an actuation indicator at the right-hand side of the left-hand set of wheels having a rocking support pivotally mounted on the same shaft and interacting with the left-hand slide, the indicator last named including a blind which in common with the blind first named is movable momentarily with the corresponding units wheel during the respective registering actuations and which does not extend to the left-hand wheel.

26. In a double register, the combination with two sets of numeral wheels mounted side by side and a horizontal shaft on which said wheels are loosely mounted of means for actuating said wheels in the registering operation including a pair of actuation slides movable vertically behind the wheels and rocking actuation transmitters at the right-hand and left-hand sides of said wheels respectively pivotally mounted on said shaft and interacting with said slides respectively,

an actuation-indicator blind carried by the right hand actuation transmitter, and an actuation indicator at the right-hand side of the left-hand set of wheels having a rocking support detachably pivoted on the same shaft and interacting with the left-hand slide, said support carrying a blind which in common with the blind first named is movable momentarily with the corresponding units wheel during the first part of each registering actuation and which does not extend to the left-hand wheel of the set.

27. In a double fare register, the combination with two registering trains arranged side by side of means for actuating the same respectively to register two kinds of fares, such means including a pair of rocking parts at the respective sides of the register appropriate to the respective trains, a pair of sliding pitmen pivoted to said parts and each provided with a guide slot and a tappet lug adjacent thereto, a pair of arms at different angles movable alternately across the paths of said lugs respectively and into planes parallel with said paths, a rock shaft extending through the slots of said pitmen on the respective ends of which said arms are fast, and a fare indicator appropriate to each train carried by said rock shaft.

28. In a double fare register, the combination with two registering trains arranged side by side of means for actuating the same respectively to register two kinds of fares, such means including a pair of rocking parts at the respective sides of the register appropriate to the respective trains, a pair of sliding pitmen pivoted to said parts and each provided with a guide slot and a tappet lug adjacent thereto, a pair of arms at different angles movable alternately across the paths of said lugs respectively and into planes parallel with said paths, a rock shaft extending through the slots of said pitmen on the respective ends of which said arms are fast, and a fare indicator appropriate to each train carried by said rock shaft.

29. In a double fare register, the combination with two registering trains arranged side by side of means for actuating the same respectively to register two kinds of fares, such means including a pair of rocking actuation transmitters at the respective sides of the register, a pair of countershafts intermittently rotated by said transmitters and spur gearing transmitting rotation from said countershafts appropriate to the respective trains, a pair of sliding pitmen pivoted to said transmitters and each provided with a guide slot and a tappet lug adjacent thereto, a pair of arms at different angles movable alternately across the paths of said lugs respectively and into planes parallel with said paths, a rock shaft extending through the

- slots of said pitmen on the respective ends of which said arms are fast, and a fare indicator appropriate to each train carried by said rock shaft.
5. 30. In a double fare register, the combination with two registering trains arranged side by side of means for actuating the same respectively to register two kinds of fares, such means including a pair of rocking parts 10 at the respective sides of the register appropriate to the respective trains, a pair of sliding pitmen pivoted to said parts and each provided with a guide slot and a tappet lug adjacent thereto, a pair of arms at different 15 angles movable alternately across the paths of said lugs respectively and into planes parallel with said paths the hub of one of said arms being provided with detent surfaces, a relatively movable detent having 20 matching surfaces, a spring by which said detent is pressed into holding contact with one or the other of said detent surfaces, a rock shaft extending through the slots of said pitmen on the respective ends of which 25 said arms are fast, and a fare indicator appropriate to each train carried by said rock shaft.
31. In a double fare register, the combination with two registering trains arranged 30 side by side of means for actuating the same respectively to register two kinds of fares, such means including a pair of rocking parts at the respective sides of the register appropriate to the respective trains, a pair of sliding 35 pitmen pivoted to said parts and each provided with a guide slot and a tappet lug adjacent thereto, a pair of arms at different angles movable alternately across the paths of said lugs respectively and into planes parallel 40 with said paths, the hub of one of said arms being provided with a V-shaped projection forming detent surfaces, a relatively movable detent having a matching V-shaped face, a spring by which said detent is pressed 45 into holding contact with one or the other of said detent surfaces, a rock shaft extending through the slots of said pitmen on the respective ends of which said arms are fast, and a fare indicator appropriate to each 50 train carried by said rock shaft.
32. In a double fare register, the combination with two registering trains arranged side by side of means for actuating the same respectively to register two kinds of fares, 55 such means including a pair of rocking parts at the respective sides of the register appropriate to the respective trains, a pair of sliding pitmen pivoted to said parts and each provided with a guide slot and a tappet lug adjacent thereto, a pair of arms at different 60 angles movable alternately across the paths of said lugs respectively and into planes parallel with said paths, the hub of one of said arms being provided with a V-shaped projection forming detent surfaces, a detent 65 lever having a matching V-shaped face, a spring by which said lever face is pressed into holding contact with one or the other of said detent surfaces, a rock shaft extending through the slots of said pitmen on the respective ends of which said arms are fast, and a fare indicator appropriate to each train carried by said rock shaft.
33. In a double fare register, the combination with two registering trains arranged side by side of means for actuating the same respectively to register two kinds of fares, such means including a pair of rocking parts at the respective sides of the register appropriate to the respective trains, a pair of sliding pitmen pivoted to said parts and each provided with a guide slot and a tappet lug adjacent thereto, a pair of arms at different angles movable alternately across the paths of said lugs respectively and into planes parallel with said paths, the hub of one of said arms being provided with a V-shaped projection forming detent surfaces, a detent lever having a matching V-shaped face, a tensile spring stretched from said lever and operating to press said face of the detent lever into holding contact with one or the other of said detent surfaces, a rock shaft extending through the slots of said pitmen on the respective ends of which said arms are fast, and a fare indicator appropriate to each train carried by said rock shaft.
34. In a double fare register, the combination with two registering trains arranged side by side of means for actuating the same respectively to register two kinds of fares, such means including a pair of rocking parts at the respective sides of the register appropriate to the respective trains, a pair of sliding pitmen pivoted to said parts and each provided with a guide slot and a tappet lug adjacent thereto, a pair of arms at different angles movable alternately across the paths of said lugs respectively and into planes parallel with said paths, the hub of one of said arms being provided with a V-shaped projection forming detent surfaces, a relatively movable detent having a matching V-shaped face, a tensile spring stretched from said lever and operating to press said face of the detent lever into holding contact with one or the other of said detent surfaces, a rock shaft extending through the slots of said pitmen on the respective ends of which said arms are fast, and a fare indicator appropriate to each train carried by said rock shaft.
35. In a double fare register, the combination with two registering trains arranged side by side of means for actuating the same respectively to register two kinds of fares, such means including a pair of rocking parts at the respective sides of the register, a pair of countershafts intermittently rotated by said transmitters and spur 130

gearing transmitting rotation from said countershafts appropriate to the respective trains, a pair of sliding pitmen pivoted to said transmitters and each provided with a guide 5 slot and a tappet lug adjacent thereto, a pair of arms at different angles movable alternately across the paths of said lugs respectively and into planes parallel with said paths, the hub of one of said arms being provided with a pair of detent surfaces, a detent 10 lever having a matching face, a tensile spring stretched from said lever and operating to press said face of the detent lever into holding contact with one or the other of said detent 15 surfaces, a rock shaft extending through the slots of said pitmen on the respective ends of which said arms are fast, and a fare indicator appropriate to each train carried by said rock shaft.

20 36. In a register, the combination with a set of decimal numeral wheels and an endwise movable and rotatable horizontal shaft on which they are loosely mounted of means for actuating said wheels in the registering operation including an actuation transmitter at the left-hand side of the wheels, means for resetting the wheels including a pulling and turning knob attached to the right-hand end of said shaft and transmission devices carried by said shaft at the left of each wheel and movable into effective position when the shaft is pulled, and means for locking said actuation transmitter at the beginning of each resetting operation including a collar 30 fast on said shaft, a lever interacting with said collar, a horizontal slide moved by said lever and a bolt moved by said slide and interlocked with said actuation transmitter when said shaft is pulled.

40 37. In a register, the combination with a set of numeral wheels and an endwise movable and rotatable horizontal shaft on which they are loosely mounted of means for actuating said wheels in the registering operation, including a rocking actuation transmitter at the left-hand side of the wheels having a peripheral locking projection, means for resetting the wheels including a pulling and turning knob attached to the right-hand 45 end of said shaft and transmission devices carried by said shaft at the left of each wheel and movable into effective position when the shaft is pulled, and means for locking said actuation transmitter at the beginning of each resetting operation including a collar fast on said shaft, a lever interacting with said collar, a horizontal slide moved by said lever and a bolt moved by said slide and interlocked with said locking projection when 50 said shaft is pulled.

38. In a register, the combination with a set of decimal numeral wheels, right-hand and left-hand frame pieces between which said wheels are mounted and an endwise 55 movable and rotatable horizontal shaft on

which said wheels are loose, of means for actuating said wheels in the registering operation including an actuation transmitter at the left-hand side of the wheels, means for resetting the wheels including a pulling and turning knob attached to the right-hand end of said shaft and transmission devices carried by said shaft at the left of each wheel and movable into effective position when the shaft is pulled, means for locking said actuation transmitter at the beginning of each resetting operation including a collar fast on said shaft, a lever interacting with said collar, a horizontal slide moved by said lever and a bolt moved by said slide and interlocked with said actuation transmitter when said shaft is pulled, and a tensile retracting spring stretched from said slide to the left-hand frame piece.

39. In a double register, the combination with two sets of decimal numeral wheels arranged side by side and an endwise movable and rotatable horizontal shaft on which they are loosely mounted of means for actuating said wheels in the registering operation, including actuation transmitters at the right-hand and left-hand sides of the respective sets, means for resetting the wheels including a pulling and turning knob attached to the right-hand end of said shaft and transmission devices carried by said shaft at the left of each wheel and movable into effective position when the shaft is pulled, a right-hand locking bolt connecting said lever and said slide, and a left-hand bolt moved by said slide, said bolts being simultaneously interlocked with the respective actuation transmitters when said shaft is pulled.

40. In a double register, the combination with two sets of decimal numeral wheels arranged side by side and an endwise movable and rotatable horizontal shaft on which they are loosely mounted of means for actuating said wheels in the registering operation, including rocking actuation transmitters pivotally mounted upon said shaft at the right-hand and left-hand sides of the respective sets and constructed with peripheral locking projections, means for resetting the wheels including a pulling and turning knob attached to the right-hand end of said shaft and transmission devices carried by said shaft at the left of each wheel and movable into effective position when the shaft is pulled, and means for locking said actuation transmitters at the beginning of each resetting operation including a collar fast on said shaft, a lever interacting with said collar, a horizontal slide moved by said lever, a right-hand locking bolt connecting said lever and said slide and a left-hand bolt moved by said slide, said bolts being simultaneously interlocked with said locking projections of the respective actuation transmitters when said shaft is pulled.

41. In a double register, the combination with two sets of decimal numeral wheels arranged side by side, right-hand and left-hand frame pieces between which said wheels are mounted and an endwise movable and rotatable horizontal shaft on which said wheels are loose, of means for actuating said wheels in the registering operation including actuation transmitters at the right-hand and left-hand sides of the respective sets, means for resetting the wheels including a pulling and turning knob attached to the right-hand end of said shaft and transmission devices carried by said shaft at the left of each wheel and movable into effective position when the shaft is pulled, means for locking said actuation transmitters at the beginning of each resetting operation including a collar fast on said shaft, a lever interacting with said collar, a horizontal slide moved by said lever, a right-hand locking bolt connecting said lever and said slide and a left-hand bolt moved by said slide, said bolts being simultaneously interlocked with the respective actuation transmitters when said shaft is pulled, and a tensile retracting spring stretched from said slide to the left-hand frame piece.

42. A register having, in combination, a series of decimal numeral wheels arranged side by side, means for actuating the units wheel step by step in the registering operation, means for transmitting such motion from said units wheel to the tens wheel including a transfer lug carried by the left-hand side of said units wheel, a transfer pinion adapted to interact with said transfer lug and a spur gear in constant mesh with said pinion attached to the right-hand side of said tens wheel, said transfer lug being adapted to contact with said pinion when said units wheel is turned in either direction, means for turning backward the numeral wheels or such of them as have been moved in the registering operation to reset them, and a locking device normally out of contact with said pinion movable into engagement therewith to lock the same during such resetting operation.

43. A register having, in combination, a series of decimal numeral wheels arranged side by side, means for actuating the units wheel step by step in the registering operation, means for transmitting such motion from said units wheel to the tens wheel including a transfer lug carried by the left-hand side of said units wheel, a transfer pinion adapted to interact with said transfer lug and a spur gear in constant mesh with said pinion attached at the right-hand side of said tens wheel, said transfer lug being adapted to contact with said pinion when said units wheel is turned in either direction, means for turning backward the numeral wheels or such of them as have been moved in the registering operation to reset them, and a slide adapted to interlock with said pinion to pre-

vent overmovement of the units wheel during such resetting operation.

44. A register having a series of decimal numeral wheels arranged side by side, means for actuating the units wheel step by step in the registering operation, means for transmitting such motion from said units wheel to the tens wheel including a transfer lug carried by the left-hand side of said units wheel, a transfer pinion adapted to interact with said transfer lug and a spur gear in constant mesh with said pinion attached to the right-hand side of said tens wheel, said transfer lug being adapted to contact with said pinion when the numeral wheel carrying the same is turned in either direction, means for turning backward the numeral wheels or such of them as have been moved in the registering operation to reset them, and a slide, movable in a path parallel to the axis of said pinion and having a projection interacting with said pinion, to lock the same during each resetting operation, whereby said pinion is adapted to interact with said transfer lug to prevent overmovement of the units wheel in such resetting operation.

45. A register having a series of decimal numeral wheels arranged side by side, means for actuating the units wheel step by step in the registering operation, means for transmitting such motion from said units wheel to the tens wheel including a transfer lug carried by the left-hand side of said units wheel, a transfer pinion adapted to interact with said transfer lug and a spur gear in constant mesh with said pinion attached to the right-hand side of said tens wheel, said transfer lug being adapted to contact with said pinion when the numeral wheel carrying the same is turned in either direction, means for turning backward the numeral wheels or such of them as have been moved in the registering operation to reset them, a rod parallel to the axis of said pinion, and a slide having a guide sleeve embracing said rod and a projection interacting with the teeth of said pinion to lock the same during such resetting operation.

46. A register having a series of decimal numeral wheels arranged side by side, means for actuating the units wheel step by step in the registering operation, means for transmitting such motion from said units wheel to the tens wheel, including a transfer lug carried by the left-hand side of said units wheel, a transfer pinion adapted to interact with said transfer lug and a spur gear in constant mesh with said pinion attached to the right-hand side of said tens wheel, said transfer lug being adapted to contact with said pinion when the numeral wheel carrying the same is turned in either direction, means for turning backward the numeral wheels or such of them as have been moved in the registering operation to reset them, a rod parallel to the

axis of said pinions, a slide having a guide sleeve embracing said rod and a projection interacting with the teeth of said pinion, and means whereby said slide is kept from swinging on said rod.

47. A register having a series of decimal numeral wheels arranged side by side, means for actuating the units wheel step by step in the registering operation, means for transmitting such motion from said units wheel to the tens wheel including a transfer lug carried by the left-hand side of said units wheel, a transfer pinion adapted to interact with said transfer lug and a spur gear in constant mesh with said pinion attached to the right-hand of said tens wheel, said transfer lug being adapted to contact with said pinion when the numeral wheel carrying the same is turned in either direction, means for turning backward the numeral wheels or such of them as have been moved in the registering operation to reset them, a slide movable parallel to the axis of said pinion and having a projection interacting with said pinion to lock the same during each resetting operation.

48. A register having a series of decimal numeral wheels arranged side by side, means for actuating the units wheel step by step in the registering operation, means for transmitting motion from said units wheel to the tens wheel, including a transfer lug carried by the left-hand side of said units wheel, a transfer pinion in the form of a small spur wheel and a star wheel of the same diameter side by side adapted to interact with said transfer lug and a spur gear in constant mesh with said pinion attached to the right-hand side of said tens wheel, said transfer lug being adapted to contact with the spur-wheel teeth of said pinion when the numeral wheel carrying the same is turned in either direction, means for turning backward the numeral wheels or such of them as have been moved in the registering operation to reset them, and a locking device normally out of contact with said pinion movable into engagement therewith to lock the same during such resetting operation.

49. A register having a series of decimal numeral wheels arranged side by side, means for actuating the units wheel step by step in the registering operation, means for transmitting motion from said units wheel to the tens wheel, including a transfer lug carried by the left-hand side of said units wheel, a transfer pinion in the form of a small spur wheel and a star wheel of the same diameter side by side adapted to interact with said transfer lug and a spur gear in constant mesh with said pinion attached to the right-hand

side of said tens wheel, said transfer lug being adapted to contact with the spur-wheel teeth of said pinion when the numeral wheel carrying the same is turned in either direction, means for turning backward the numeral wheels or such of them as have been moved in the registering operation to reset them, and a slide adapted to interact with said pinion to lock the same during such resetting operation.

50. A register having a series of decimal numeral wheels arranged side by side, means for actuating the units wheel step by step in the registering operation, means for transmitting motion from said units wheel to the tens wheel, including a transfer lug carried by the left-hand side of said units wheel, a transfer pinion in the form of a small spur wheel and a star wheel of the same diameter side by side adapted to interact with said transfer lug and a spur gear in constant mesh with said pinion attached to the right-hand side of said tens wheel, said transfer lug being adapted to contact with the spur wheel teeth of said pinion when the numeral wheel carrying the same is turned in either direction, means for turning backward the numeral wheels or such of them as have been moved in the registering operation to reset them, and a slide movable in a path parallel to the axis of said pinion and having a projection interacting with said pinion to lock the same during the resetting operation.

51. A register having a series of decimal numeral wheels arranged side by side, means for actuating the units wheel step by step in the registering operation, means for transmitting motion from said units wheel to the tens wheel, including a transfer lug carried by the left-hand side of said units wheel, a transfer pinion in the form of a small spur wheel and a star wheel of the same diameter side by side adapted to interact with said transfer lug and a spur gear in constant mesh with said pinion attached to the right-hand side of said tens wheel, said transfer lug being adapted to contact with the spur-wheel teeth of said pinion when the numeral wheel carrying the same is turned in either direction, means for turning backward the numeral wheels or such of them as have been moved in the registering operation to reset them, a rod parallel to the axis of said pinion and a slide having a guide sleeve embracing said rod and a projection interacting with the teeth of said pinion to lock the same during such resetting operation.

52. A register having a series of decimal numeral wheels arranged side by side, means for actuating the units wheel step by step in the registering operation, means for transmitting motion from said units wheel to the tens wheel, including a transfer lug carried by the left-hand side of said units wheel, a transfer pinion in the form of a

small spur wheel and a star wheel of the same diameter side by side adapted to interact with said transfer lug and a spur gear in constant mesh with said pinion attached to 5 the right-hand side of said tens wheel, said transfer lug being adapted to contact with the spur-wheel teeth of said pinion when the numeral wheel carrying the same is turned in either direction, means for turning backward the numeral wheels or such of them as have been moved in the registering operation to reset them, a rod parallel to the axis of said pinion, a slide having a guide sleeve embracing said rod and a projection interacting with the teeth of said pinion to lock the same during such resetting operation, and means whereby said slide is kept from swinging on said rod.

53. A register having a series of decimal numeral wheels arranged side by side, means for actuating the units wheel step by step in the registering operation, means for transmitting motion from said units wheel to the tens wheel, including a transfer lug 20 carried by the left-hand side of said units wheel, a transfer pinion in the form of a small spur wheel and a star wheel of the same diameter side by side adapted to interact with said transfer lug and a spur gear in constant mesh with said pinion attached to the right-hand side of said units wheel, said transfer lug being adapted to contact with the spur-wheel teeth of said pinion when the numeral wheel carrying the same is turned in either direction, means for turning backward the numeral wheels or 25 such of them as have been moved in the registering operation to reset them, and a slide adapted to interlock with said pinion during such resetting operation.

54. A register having a series of decimal numeral wheels arranged side by side, means for turning the units wheel step by step in the registering operation, means for transmitting such motion from wheel to wheel including a suitably spaced pair of spur teeth carried by the left-hand side of said units wheel, a transfer pinion in the form of a small spur wheel and a star wheel of the same diameter side by side adapted to mesh by its star-wheel teeth with the interdental space of said pair of teeth and a spur gear in constant mesh with the spur-wheel teeth of said pinion carried by the right-hand side of the tens wheel, said pair of teeth being adapted to contact with the spur-wheel teeth of said pinion when the numeral wheel carrying the same is turned in either direction, means for 30 turning backward the numeral wheels or

such of them as have been moved in the registering operation to reset them, and a locking device normally out of contact with said pinion movable into engagement therewith to lock the same during such resetting operation.

55. A register having a series of decimal numeral wheels arranged side by side, means for turning the units wheel step by step in the registering operation, means for transmitting such motion from wheel to wheel including a suitably spaced pair of spur teeth carried by the left-hand side of said units wheel, a transfer pinion in the form of a small spur wheel and a star wheel of the same diameter side by side adapted to mesh by its star-wheel teeth with the interdental space of said pair of teeth and a spur gear in constant mesh with the spur-wheel teeth of said pinion carried by the right-hand side of the tens wheel, said pair of teeth being adapted to contact with the spur-wheel teeth of said pinion when the numeral wheel carrying the same is turned in either direction, means for turning backward the numeral wheels or 35 such of them as have been moved in the registering operation to reset them, and a slide adapted to interlock with said pinion during such resetting operation.

56. A register having a series of decimal numeral wheels arranged side by side, means for turning the units wheel step by step in the registering operation, means for transmitting such motion from wheel to wheel including a suitably spaced pair of spur teeth carried by the left-hand side of said units wheel, a transfer pinion in the form of a small spur wheel and a star wheel of the same diameter side by side adapted to mesh by its star-wheel teeth with the interdental space of said pair of teeth and a spur gear in constant mesh with the spur-wheel teeth of said pinion carried by the right hand side of the tens wheel, said pair of teeth being adapted to contact with the spur-wheel teeth of said pinion when the numeral wheel carrying the same is turned in either direction, means for turning backward the numeral wheels or such of them as have been moved in the registering operation to reset them, and a slide movable parallel to the axis of said pinion and having a projection interacting with said pinion to lock the same during such resetting operation.

57. A register having a series of decimal numeral wheels arranged side by side, means for turning the unitswheel step by step in the registering operation, means for transmitting such motion from wheel to wheel including a suitably spaced pair of spur teeth carried by the left-hand side of said units wheel, a transfer pinion in the form of a small spur wheel and a star wheel of the same diameter side by side adapted to mesh by its star-wheel teeth with the interdental space of said pair of teeth of

teeth and a spur gear in constant mesh with the spur-wheel teeth of said pinion carried by the right-hand side of the tens wheel, said pair of teeth being adapted to contact with the spur-wheel teeth of said pinion when the

5 numeral wheel carrying the same is turned in either direction, means for turning backward the numeral wheels or such of them as have been moved in the registering operation to reset them, a rod parallel to the axis of said pinion, and a slide having a guide sleeve embracing said rod and a projection interacting with said pinion to lock the same during such resetting operation.

15 58. A register having a series of decimal numeral wheels arranged side by side, means for turning the units wheel step by step in the registering operation, means for transmitting such motion from wheel to wheel including a suitably spaced pair of spur teeth carried by the left-hand side of said units wheel, a transfer pinion in the form of a small spur wheel and a star wheel of the same diameter side by side adapted to mesh by its 20 star-wheel teeth with the interdental space of said pair of teeth and a spur gear in constant mesh with the spur-wheel teeth of said pinion carried by the right-hand side of the tens wheel, said pair of teeth being adapted

25 to contact with the spur-wheel teeth of said pinion when the numeral wheel carrying the same is turned in either direction, means for turning backward the numeral wheels or such of them as have been moved in the registering operation to reset them, a rod parallel to the axis of said pinion, a slide having a guide sleeve embracing said rod and a projection interacting with said pinion to lock the same during such resetting operation, and means 30 whereby said slide is kept from swinging on said rod.

59. A register having a series of decimal numeral wheels arranged side by side, means for turning the units wheel step by step in the registering operation, means for transmitting such motion from wheel to wheel including a suitably spaced pair of spur teeth carried by the left-hand side of said units wheel, a transfer pinion in the form of a small spur wheel and a star wheel of the same diameter side by side adapted to mesh by its star-wheel teeth with the interdental space of said pair of teeth and a spur gear in constant mesh with the spur-wheel teeth of said 50 pinion carried by the right-hand side of the tens wheel, said pair of teeth being adapted to contact with the spur-wheel teeth of said pinion when the numeral wheel carrying the same is turned in either direction, means for turning backward the numeral wheels or such of them as have been moved in the registering operation to reset them, a slide movable parallel to the axis of said pinion and having a projection interacting with said 55 pinion to lock the same during each resetting

operation and a tensile spring interacting with said slide stretched parallel therewith and serving to keep said projection out of contact with said pinion during the registering operation.

60. A register having, in combination, a series of decimal numeral wheels arranged side by side, means for actuating the units wheel step by step in the registering operation, means for transmitting such motion from wheel to wheel including a transfer lug carried by the left-hand side of each wheel having a wheel of higher value at its left, a transfer pinion interacting with such transfer lug and a spur gear in constant mesh with such pinion attached to the right-hand side of each wheel to the left, each transfer lug being adapted to contact with the corresponding pinion when the numeral wheel carrying the same is turned in either direction, means for turning backward the numeral wheels or such of them as have been moved in the registering operation to reset them, and a locking device for each pinion normally out of contact therewith movable into engagement therewith to lock the same during such resetting operation.

61. A register having, in combination, a series of decimal numeral wheels arranged side by side, means for actuating the units wheel step by step in the registering operation, means for transmitting such motion from wheel to wheel including a transfer lug carried by the left-hand side of each wheel having a wheel of higher value at its left, a transfer pinion interacting with such transfer lug and a spur gear in constant mesh with such pinion attached to the right-hand side of each wheel to the left, each transfer lug being adapted to contact with the corresponding pinion when the numeral wheel carrying the same is turned in either direction, means for turning backward the numeral wheels or such of them as have been moved in the registering operation to reset them, and a slide interacting with each of said pinions to lock the same during such resetting operation.

62. A register having, in combination, a series of decimal numeral wheels arranged side by side, means for actuating the units wheel step by step in the registering operation, means for transmitting such motion from wheel to wheel including a transfer lug carried by the left-hand side of each wheel having a wheel of higher value at its left, a transfer pinion interacting with such transfer lug and a spur gear in constant mesh with such pinion attached to the right-hand side of each wheel to the left, each transfer lug being adapted to contact with the corresponding pinion when the numeral wheel carrying the same is turned in either direction, means for turning backward the numeral wheels or such of them as have been moved in the registering operation to reset them, and a slide interacting with each of said pinions to lock the same during each resetting

moved in the registering operation to reset them, and a slide movable in a path parallel to the axis of said pinions having projections interacting with the several pinions to lock the same during the resetting operation.

63. A register having, in combination, a series of decimal numeral wheels arranged side by side, means for actuating the units wheel step by step in the registering operation, means for transmitting such motion from wheel to wheel including a transfer lug carried by the left-hand side of each wheel having a wheel of higher value at its left, a transfer pinion interacting with such transfer lug and a spur gear in constant mesh with such pinion attached to the right-hand side of each wheel to the left, each transfer lug being adapted to contact with the corresponding pinion when the numeral wheel carrying the same is turned in either direction, means for turning backward the numeral wheels or such of them as have been moved in the registering operation to reset them, a rod parallel to the axis of said pinions and a slide having guide sleeves embracing said rod and projections interacting with the teeth of the several pinions to lock the same during such resetting operation.

64. A register having, in combination, a series of decimal numeral wheels arranged side by side, means for actuating the units wheel step by step in the registering operation, means for transmitting such motion from wheel to wheel including a transfer lug carried by the left-hand side of each wheel having a wheel of higher value at its left, a transfer pinion interacting with such transfer lug and a spur gear in constant mesh with such pinion attached to the right-hand side of each wheel to the left, each transfer lug being adapted to contact with the corresponding pinion when the numeral wheel carrying the same is turned in either direction, means for turning backward the numeral wheels or such of them as have been moved in the registering operation to reset them, a rod parallel to the axis of said pinions, a slide having guide sleeves embracing said rod and projections interacting with the teeth of said pinions to lock the same during such resetting operation, and means whereby said slide is kept from swinging on said rod.

65. A register having, in combination, a series of decimal numeral wheels arranged side by side, means for actuating the units wheel step by step in the registering operation, means for transmitting such motion from wheel to wheel including a transfer lug carried by the left-hand side of each wheel having a wheel of higher value at its left, a transfer pinion interacting with such transfer lug and a spur gear in constant mesh with such pinion attached to the right-hand side of each wheel to the left, each transfer lug being adapted to contact with the corresponding pinion

when the numeral wheel carrying the same is turned in either direction, means for turning backward the numeral wheels or such of them as have been moved in the registering operation to reset them, a slide movable parallel to the axis of said pinions and having projections interacting with the teeth of said pinions to lock the same during such resetting operation, and a tensile spring interacting with said slide stretched parallel therewith and serving to keep said projections out of contact with said pinions during the registering operation.

66. A register having, in combination, a series of decimal numeral wheels arranged side by side, means for actuating the units wheel in the registering operation, means for transmitting such motion from wheel to wheel, including a transfer lug carried by the left-hand side of each numeral wheel having a wheel of higher value at its left, a transfer pinion interacting with each transfer lug and a spur gear in constant mesh with a transfer pinion attached to the right-hand side of the adjoining numeral wheel, each transfer lug being adapted to contact effectively with the pinion interacting therewith when the numeral wheel carrying the same is turned in either direction, means for turning backward the numeral wheels or such of them as have been moved in the registering operation to reset them, a locking device normally out of contact whereby each transfer pinion is locked to prevent overmovement during each resetting operation, and means for stopping the left-hand numeral wheel at zero in such resetting operation.

67. A register having, in combination, a series of decimal numeral wheels arranged side by side, means for actuating the units wheel in the registering operation, means for transmitting such motion from wheel to wheel, including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, means for turning backward the numeral wheels or such of them as have been moved in the registering operation to reset them, a normally retracted slide interacting with each transfer pinion to lock the same during each resetting operation, and means for stopping the left-hand numeral wheel at zero in such resetting operation.

68. A register having, in combination, a series of decimal numeral wheels arranged side by side, means for actuating the units wheel in the registering operation, means for transmitting such motion from wheel to

- wheel, including a transfer lug carried by the left-hand side of each numeral wheel having a wheel of higher value at its left, a transfer pinion interacting with each transfer lug and 5 a spur gear in constant mesh with one of said pinions attached to the right-hand side of each adjoining numeral wheel, each transfer lug being adapted to contact effectively with the pinion interacting therewith when the 10 numeral wheel carrying the same is turned in either direction, means for turning backward the numeral wheels or such of them as have been moved in the registering operation to reset them, a slide common to all the pinions 15 having projections interacting with the several transfer pinions to lock the same during each resetting operation, and means for stopping the left-hand numeral wheel at zero in such resetting operation.
- 20 69. A register having, in combination, a series of decimal numeral wheels arranged side by side, means for actuating the units wheel in the registering operation, means for transmitting such motion from wheel to 25 wheel, including a transfer lug carried by the left-hand side of each numeral wheel having a wheel of higher value at its left, a transfer pinion interacting with each transfer lug and a spur gear in constant mesh with one of said 30 pinions attached to the right-hand side of each adjoining numeral wheel, each transfer lug being adapted to contact effectively with the pinion interacting therewith when the numeral wheel carrying the same is turned in 35 either direction, means for turning backward the numeral wheels or such of them as have been moved in the registering operation to reset them, a slide parallel to the axis of said transfer pinions having projections interacting with the teeth of the several pinions to lock the same during such resetting operation, a tensile spring interacting with said slide and adapted to keep said projections out of contact with said pinions during the registering 40 operation, and means for stopping the left-hand numeral wheel at zero in each resetting operation.
- 45 70. A register having, in combination, a series of decimal numeral wheels arranged side by side, means for actuating the units wheel in the registering operation, means for transmitting such motion from wheel to 50 wheel, including a transfer lug carried by the left-hand side of each numeral wheel having a wheel of higher value at its left, a transfer pinion interacting with each transfer lug and a spur gear in constant mesh with one of said 55 pinions attached to the right-hand side of each adjoining numeral wheel, each transfer lug being adapted to contact effectively with the pinion interacting therewith when the numeral wheel carrying the same is turned in 60 either direction, means for turning backward the numeral wheels or such of them as have been moved in the registering operation to reset them, a rod parallel to the axis of said transfer pinions, a slide having guide sleeves 65 embracing said rod and projections interacting with the teeth of said pinions to lock the same during each resetting operation, and means for stopping the left-hand numeral wheel at zero in such resetting operation.
- 70 71. A register having, in combination, a series of decimal numeral wheels arranged side by side, means for actuating the units wheel in the registering operation, means for transmitting such motion from wheel to 75 wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the 80 numeral wheel carrying the same is turned in either direction, means for turning backward the numeral wheels or such of them as have been moved in the registering operation to reset them, a slide parallel to the axis of said transfer pinions having projections interacting with the teeth of the several pinions to lock the same during such resetting operation, a tensile spring interacting with said slide and adapted to keep said projections out of contact with said pinions during the registering 85 operation, and means for stopping the left-hand numeral wheel at zero in each resetting operation.
- 75 72. A register having, in combination, a series of decimal numeral wheels arranged side by side, means for actuating the units wheel in the registering operation, means for transmitting such motion from wheel to 90 wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the 95 numeral wheel carrying the same is turned in either direction, means for turning backward the numeral wheels or such of them as have been moved in the registering operation to reset them, a locking device normally out of contact whereby each pinion is locked to prevent overmovement during the resetting operation, a rod on which the several pinions are loosely mounted, a spring-pressed dog pivoted on this rod and a ring attached to the left-hand side of the left-hand numeral wheel and provided with a peripheral stop notch interacting with said dog at the end of such resetting operation.
- 100 73. A register having, in combination, a series of decimal numeral wheels arranged side by side, means for actuating the units 105 wheel in the registering operation, means for transmitting such motion from wheel to 110 wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the 115 numeral wheel carrying the same is turned in either direction, means for turning backward the numeral wheels or such of them as have been moved in the registering operation to reset them, a locking device normally out of contact whereby each pinion is locked to prevent overmovement during the resetting operation, a rod on which the several pinions are loosely mounted, a spring-pressed dog pivoted on this rod and a ring attached to the left-hand side of the left-hand numeral wheel and provided with a peripheral stop notch interacting with said dog at the end of such resetting operation.
- 120 74. A register having, in combination, a series of decimal numeral wheels arranged side by side, means for actuating the units 125 wheel in the registering operation, means for transmitting such motion from wheel to 130 wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, means for turning backward the numeral wheels or such of them as have been moved in the registering operation to reset them, a slide parallel to the axis of said transfer pinions having projections interacting with the teeth of the several pinions to lock the same during such resetting operation, a tensile spring interacting with said slide and adapted to keep said projections out of contact with said pinions during the registering operation, and means for stopping the left-hand numeral wheel at zero in each resetting operation.

- wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, means for turning backward the numeral wheels or such of them as have been moved in the registering operation to reset them, a slide normally out of contact whereby each pinion is locked to prevent overmovement during the resetting operation, a rod on which the several pinions are loosely mounted, a spring-pressed dog pivoted on this rod, and a ring attached to the left-hand side of the left-hand numeral wheel and provided with a peripheral stop notch interacting with said dog at the end of such resetting operation.

74. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, means for turning backward the numeral wheels or such of them as have been moved in the registering operation to reset them, a slide common to all the pinions having projections interacting with the several pinions to lock the same during each resetting operation, a rod on which the several pinions are loosely mounted, a spring pressed dog pivoted on this rod, and a ring attached to the left-hand side of the left-hand numeral wheel and provided with a peripheral stop notch interacting with said dog at the end of such resetting operation.

75. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer

lug being adapted to contact effectively with the pinion interacting therewith when the wheel carrying the same is turned in either direction, means for turning backward the numeral wheels or such of them as have been moved in the registering operation to reset them, a rod parallel to the axis of said transfer pinions, a slide having guide sleeves embracing said rod and projections interacting with the teeth of said pinions to lock the same during each resetting operation, a rod on which the several pinions are loosely mounted, a spring pressed dog pivoted on this rod, and a ring attached to the left-hand side of the left-hand numeral wheel and provided with a peripheral stop notch interacting with said dog at the end of such resetting operation.

76. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, means for turning backward the numeral wheels or such of them as have been moved in the registering operation to reset them, a rod parallel to the axis of said trip pinions, a slide having a guide sleeve embracing said rod and projections interacting with the teeth of said pinions to lock the same during each resetting operation, means whereby said slide is kept from swinging on said rod, a rod on which the several pinions are loosely mounted, a spring-pressed dog pivoted on this rod, and a ring attached to the left-hand side of the left-hand numeral wheel and provided with a peripheral stop notch interacting with said dog at the end of such resetting operation.

77. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, means for turning backward 115
120
125
130

the numeral wheels or such of them as have been moved in the registering operation to reset them, a slide parallel with the axis of said pinions having projections interacting with 5 the teeth of the several pinions to lock the same during such resetting operation, a tensile spring interacting with said slide and adapted to keep said projections out of contact with said pinions during the registering 10 operation, a rod on which the several pinions are loosely mounted, a spring-pressed dog pivoted on this rod, and a ring attached to the left-hand side of the left-hand numeral wheel and provided with a peripheral stop 15 notch interacting with said dog at the end of such resetting operation.

78. A register having, in combination, a series of decimal numeral wheels arranged side by side, means for actuating the units 20 wheel in the registering operation, means for transmitting such motion from wheel to wheel including a transfer lug carried by the left-hand side of each numeral wheel having a wheel of higher value at its left, a transfer 25 pinion interacting with each transfer lug and a spur gear in constant mesh with one of said pinions attached to the right-hand side of each adjoining numeral wheel, said transfer lug being adapted to contact effectively with 30 the pinion interacting therewith when the numeral wheel carrying the same is turned in either direction, a rotatable shaft common to said numeral wheels, a resetting knob by which said shaft is turned, means for transmitting 35 backward resetting motion from said shaft to said numeral wheels or such of them as have been moved in the registering operation, and a locking device normally out of contact whereby each pinion is locked 40 to prevent overmovement during such resetting operation.

79. A register having, in combination, a series of decimal numeral wheels arranged side by side, means for actuating the units 45 wheel in the registering operation, means for transmitting such motion from wheel to wheel including a transfer lug carried by the left-hand side of each numeral wheel having a wheel of higher value at its left, a transfer 50 pinion interacting with each transfer lug and a spur gear in constant mesh with one of said pinions attached to the right-hand side of each adjoining numeral wheel, each transfer lug being adapted to contact effectively with 55 the pinion interacting therewith when the numeral wheel carrying the same is turned in either direction, a rotatable shaft common to said numeral wheels, a resetting knob by which said shaft is turned, means for transmitting 60 backward resetting motion from said shaft to said numeral wheels or such of them as have been moved in the registering operation, and a slide interacting with each pinion to lock the same during such resetting opera- 65 tion.

80. A register having, in combination, a series of decimal numeral wheels arranged side by side, means for actuating the units wheel in the registering operation, means for transmitting such motion from wheel to 70 wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned 75 in either direction, a rotatable shaft common to said numeral wheels, a resetting knob by which said shaft is turned, means for transmitting backward resetting motion from said shaft to said numeral wheels or such of them 80 as have been moved in the registering operation, and a slide common to all the pinions having projections interacting with the several pinions to lock the same during such resetting operation. 85

81. A register having, in combination, a series of decimal numeral wheels arranged side by side, means for actuating the units wheel in the registering operation, means for transmitting such motion from wheel to 90 wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned 95 in either direction, a rotatable shaft common to said numeral wheels, a resetting knob by which said shaft is turned, means for transmitting backward resetting motion from said shaft to said numeral wheels or 100 such of them as have been moved in the registering operation, and a rod parallel to the axis of said pinions, and a slide having guide sleeves embracing said rod and projections interacting with the teeth of said pinions to 110 lock the same during such resetting operation. 115

82. A register having, in combination, a series of decimal numeral wheels arranged side by side, means for actuating the units 120 wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effect- 125 130

ively with the pinion interacting therewith when the numeral wheel carrying the same is turned in either direction, a rotatable shaft common to said numeral wheels, a resetting knob by which said shaft is turned, means for transmitting backward resetting motion from said shaft to said numeral wheels or such of them as have been moved in the registering operation, a rod parallel to the axis of said pinions, a slide having guide sleeves embracing said rod and projections interacting with the teeth of said pinions to lock the same during such resetting operation, and means whereby said slide is kept from swinging on said rod.

83. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, a rotatable shaft common to said numeral wheels, a resetting knob by which said shaft is turned, means for transmitting backward resetting motion from said shaft to said numeral wheels or such of them as have been moved in the registering operation, a slide parallel to the axis of said pinions having projections interacting with the teeth of the several pinions to lock the same during such resetting operation, and a tensile spring interacting with said slide and adapted to keep said projections out of contact with said pinions during the registering operation.

84. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, a rotatable shaft common to said numeral wheels, a resetting knob by which said shaft is turned, means for disconnecting the several numeral wheels from said actuating and transmitting means and for transmitting backward resetting motion

from said shaft to said numeral wheels or such of them as have been moved in the registering operation, and a locking device normally out of contact whereby each pinion is locked to prevent overmovement in said resetting operation.

85. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, a rotatable shaft common to said numeral wheels, a resetting knob by which said shaft is turned, means for disconnecting the several numeral wheels from said actuating and transmitting means and for transmitting backward resetting motion from said shaft to said numeral wheels or such of them as have been moved in the registering operation, and a slide normally out of contact interacting with each pinion to lock the same during such resetting operation.

86. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the numeral wheel carrying the same is turned in either direction, a rotatable shaft common to said numeral wheels, a resetting knob by which said shaft is turned, means for disconnecting the several numeral wheels from said actuating and transmitting means and for transmitting backward resetting motion from said shaft to said numeral wheels or to such of them as have been moved in the registering operation, and a slide common to all the pinions having projections interacting with the several pinions to lock the same during such resetting operation.

87. A register having, in combination, a series of decimal numeral wheels arranged side by side, means for actuating the units wheel in the registering operation, means for transmitting such motion from wheel to

wheel including a transfer lug carried by the left-hand side of each numeral wheel having a wheel of higher value at its left, a transfer pinion interacting with each transfer lug and 5 a spur gear in constant mesh with one of said pinions attached to the right-hand side of each adjoining numeral wheel, each transfer lug being adapted to contact effectively with the pinion interacting therewith when the 10 numeral wheel carrying the same is turned in either direction, a rotatable shaft common to said numeral wheels, a resetting knob by which said shaft is turned, means for disconnecting the several numeral wheels from said 15 actuating and transmitting means and for transmitting backward resetting motion from said shaft to said numeral wheels or such of them as have been moved in the registering operation, a rod parallel to the axis 20 of said pinions, and a slide having guide sleeves embracing said rod and projections interacting with the teeth of said pinions to lock the same during such resetting operation.

88. A register having, in combination, a 25 series of decimal numeral wheels arranged side by side, means for actuating the units wheel in the registering operation, means for transmitting such motion from wheel to wheel including a transfer lug carried by the 30 left-hand side of each numeral wheel having a wheel of higher value at its left, a transfer pinion interacting with each transfer lug and a spur gear in constant mesh with one of said pinions attached to the right-hand side of 35 each adjoining numeral wheel, each transfer lug being adapted to contact effectively with the pinion interacting therewith when the numeral wheel carrying the same is turned in either direction, a rotatable shaft common 40 to said numeral wheels, a resetting knob by which said shaft is turned, means for disconnecting the several numeral wheels from said actuating and transmitting means and for transmitting backward resetting motion 45 from said shaft to said numeral wheels or such of them as have been moved in the registering operation, a rod parallel to the axis of said pinions, a slide having guide sleeves embracing said rod and projections interacting 50 with the teeth of said pinions to lock the same during such resetting operation, and means whereby said slide is kept from swinging on said rod.

89. A register having, in combination, a 55 series of decimal numeral wheels arranged side by side, means for actuating the units wheel in the registering operation, means for transmitting such motion from wheel to wheel including a transfer lug carried by the 60 left-hand side of each numeral wheel having a wheel of higher value at its left, a transfer pinion interacting with each transfer lug and a spur gear in constant mesh with one of 65 said pinions attached to the right-hand side of each adjoining numeral wheel, each transfer

lug being adapted to contact effectively with the pinion interacting therewith when the numeral wheel carrying the same is turned in either direction, a rotatable shaft common to said numeral wheels, a resetting knob by which said shaft is turned, means for disconnecting the several numeral wheels from said actuating and transmitting means and for transmitting backward resetting motion from said shaft to said numeral wheels 70 or such of them as have been moved in the registering operation, a slide parallel to the axis of said pinions having projections interacting with the teeth of the several pinions to lock the same during such resetting operation, and a tensile spring interacting with said slide and adapted to keep said projections out of contact with said pinions during the registering operation.

90. A register having, in combination, a 85 series of decimal numeral wheels arranged side by side, means for actuating the units wheel in the registering operation, means for transmitting such motion from wheel to wheel including a transfer lug carried by the 90 left-hand side of each numeral wheel having a wheel of higher value at its left, a transfer pinion interacting with each transfer lug and a spur gear in constant mesh with one of said pinions attached to the right-hand side of 95 each adjoining numeral wheel, each transfer lug being adapted to contact effectively with the pinion interacting therewith when the wheel carrying the same is turned in either direction, an endwise movable and rotatable 100 shaft common to said numeral wheels, a resetting knob by which said shaft is pulled and turned, means for transmitting backward resetting motion from said shaft to said numeral wheels or such of them as have been 105 moved in the registering operation, a locking device normally out of contact whereby each pinion is locked to prevent overmovement during the resetting operation, and a retracting spring common to said shaft and said locking device.

91. A register having, in combination, a 115 series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and 120 a spur gear in constant mesh with one of said pinions attached to the right-hand side of each adjoining numeral wheel, each transfer lug being adapted to contact effectively with the pinion interacting therewith when the 125 wheel carrying the same is turned in either direction, an endwise movable and rotatable shaft common to said numeral wheels, a resetting knob by which said shaft is pulled and turned, means for transmitting back- 130

ward resetting motion from said shaft to said numeral wheels or such of them as have been moved in the registering operation, a normally retracted slide interacting with each transfer pinion to lock the same during such resetting operation, and a retracting spring common to said shaft and said slide.

92. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of each adjoining numeral wheel, each transfer lug being adapted to contact effectively with the pinion interacting therewith when the wheel carrying the same is turned in either direction, an endwise movable and rotatable shaft common to said numeral wheels, a resetting knob by which said shaft is pulled and turned, means for transmitting backward resetting motion from said shaft to said numeral wheels or such of them as have been moved in the registering operation, a slide common to all the pinions having projections interacting with the several pinions to lock the same during such resetting operation, and a retracting spring common to said shaft and said slide.

93. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of the adjoining numeral wheel, each transfer lug being adapted to contact effectively with the pinion interacting therewith when the wheel carrying the same is turned in either direction, an endwise movable and rotatable shaft common to said numeral wheels, a resetting knob by which said shaft is pulled and turned, means for transmitting backward resetting motion from said shaft to said numeral wheels or such of them as have been moved in the registering operation, a rod parallel with said shaft, a slide having guide sleeves embracing said rod and projections interacting with the teeth of said pinions to lock the same during such resetting operation, and a retracting spring common to said shaft and said slide.

94. A register having, in combination, a series of decimal numeral wheels arranged side by side, means for actuating the units

wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of the adjoining numeral wheel, each transfer lug being adapted to contact effectively with the pinion interacting therewith when the wheel carrying the same is turned in either direction, an endwise movable and rotatable shaft common to said numeral wheels, a resetting knob by which said shaft is pulled and turned, means for transmitting backward resetting motion from said shaft to said numeral wheels or such of them as have been moved in the registering operation, a rod parallel with said shaft, a slide having guide sleeves embracing said rod and projections interacting with the teeth of said pinions to lock the same during such resetting operation, means whereby said slide is kept from swinging on said rod, and a retracting spring common to said shaft and said slide.

95. A register having, in combination, a series of decimal numeral wheels arranged side by side, means for actuating the units wheel in the registering operation, means for transmitting such motion from wheel to wheel including a transfer lug carried by the left-hand side of each numeral wheel having a wheel of higher value at its left, a transfer pinion interacting with each transfer lug and a spur gear in constant mesh with one of said pinions attached to the right-hand side of the adjoining numeral wheel, each transfer lug being adapted to contact effectively with the pinion interacting therewith when the wheel carrying the same is turned in either direction, an endwise movable and rotatable shaft common to said numeral wheels, a resetting knob by which said shaft is pulled and turned, means for transmitting backward resetting motion from said shaft to said numeral wheels or such of them as have been moved in the registering operation, a slide parallel with said shaft having projections interlocking with the teeth of the several pinions in such resetting operation, and a tensile spring stretched parallel with said slide and operating to retract said shaft and to keep said projections out of contact with said pinions during the registering operation.

96. A register having, in combination, decimal numeral wheels arranged side by side, means for actuating the units wheel in the registering operation, means for transmitting such motion from wheel to wheel including a transfer lug carried by the left-hand side of said units wheel, a transfer pinion interacting with said lug and a spur gear in constant mesh with said pinion, said lug

- being adapted to contact effectively with said pinion when said units wheel is turned in either direction, an endwise movable and rotatable shaft common to said numeral wheels, a resetting knob by which said shaft is pulled and turned, means for transmitting backward resetting motion from said shaft to said numeral wheels individually, a normally retracted locking device moved by 5 said shaft and interacting with said pinion to lock the same against overmovement in the resetting operation, and a retracting spring common to said shaft and said locking device.
- 15 97. A register having, in combination, decimal numeral wheels arranged side by side, means for actuating the units wheel in the registering operation, means for transmitting such motion from wheel to wheel including a transfer lug carried by the left-hand side of said units wheel, a transfer pinion interacting with said lug and a spur gear in constant mesh with said pinion, said lug being adapted to contact effectively with 20 said pinion when said units wheel is turned in either direction, an endwise movable and rotatable shaft common to said numeral wheels, a resetting knob by which said shaft is pulled and turned, means for transmitting backward resetting motion from said shaft to 25 said numeral wheels individually, a normally retracted slide interlocking with said pinion to prevent overmovement in the resetting operation, and a retracting spring common 30 to said shaft and said slide.
98. A register having, in combination, decimal numeral wheels arranged side by side, means for actuating the units wheel in the registering operation, means for transmitting such motion from wheel to wheel including a transfer lug carried by the left-hand side of said units wheel, a transfer pinion interacting with said lug and a spur gear in constant mesh with said pinion, said 45 lug being adapted to contact effectively with said pinion when said units wheel is turned in either direction, an endwise movable and rotatable shaft common to said numeral wheels, a resetting knob by which said shaft is pulled and turned, means for transmitting backward resetting motion from said shaft to 50 said numeral wheels individually, a normally retracted slide parallel with said shaft having a projection which interacts with the teeth of said pinion to lock the same against overmovement in the resetting operation, and a retracting spring common to said shaft and said slide.
- 55 99. A register having, in combination, decimal numeral wheels arranged side by side, means for actuating the units wheel in the registering operation, means for transmitting such motion from wheel to wheel including a transfer lug carried by the left-hand side of said units wheel, a transfer pin- 60
- 70 ion interacting with said lug and a spur gear in constant mesh with said pinion, said lug being adapted to contact effectively with said pinion when said units wheel is turned in either direction, an endwise movable and rotatable shaft common to said numeral wheels, a resetting knob by which said shaft is pulled and turned, means for transmitting backward resetting motion from said shaft to 75 said numeral wheels individually, a rod parallel with said shaft, a slide having a guide sleeve embracing said rod and a projection which interacts with the teeth of said pinion to lock the same against overmovement in the resetting operation, and a retracting spring common to said shaft and 80 said slide.
- 85 100. A register having, in combination, decimal numeral wheels arranged side by side, means for actuating the units wheel in the registering operation, means for transmitting such motion from wheel to wheel including a transfer lug carried by the left-hand side of said units wheel, a transfer pinion interacting with said lug and a spur gear in constant mesh with said pinion, said lug being adapted to contact effectively with 90 said pinion when said units wheel is turned in either direction, an endwise movable and rotatable shaft common to said numeral wheels, a resetting knob by which said shaft is pulled and turned, means for transmitting backward resetting motion from said shaft to 95 said numeral wheels individually, rods parallel with said shaft one of which supports said pinion, a normally retracted slide having a guide sleeve embracing another of said rods and having a projection which interlocks with the teeth of said pinion during the resetting operation and another projection which interacts with the pinion-supporting rod to prevent said slide from swinging under strain, and a retracting spring common to 100 said shaft and said slide.
- 105 101. A register having, in combination, decimal numeral wheels arranged side by side, means for actuating the units wheel in the registering operation, means for transmitting such motion from wheel to wheel including a transfer lug carried by the left-hand side of said units wheel, a transfer pinion interacting with said lug and a spur gear in constant mesh with said pinion, said lug being adapted to contact effectively with 110 said pinion when said units wheel is turned in either direction, an endwise movable and rotatable shaft common to said numeral wheels, a resetting knob by which said shaft is pulled and turned, means for transmitting backward resetting motion from said shaft to 115 said numeral wheels individually, a normally retracted slide parallel with said shaft having a projection which locks said pinion in such resetting operation, and a tensile spring stretched parallel with said slide and 120
- 125 130

op rating to retract said shaft and to keep said locking projection out of contact with said pinion during such resetting operation.

102. A register having, in combination, 5 decimal numeral wheels arranged side by side, means for actuating the units wheel in the registering operation, means for transmitting such motion from wheel to wheel including a transfer lug carried by the left-hand side of said units wheel, a transfer pinion interacting with said lug and a spur gear in constant mesh with said pinion, said lug being adapted to contact effectively with said pinion when said units wheel is turned 10 in either direction, an endwise movable and rotatable shaft common to said numeral wheels, a resetting knob by which said shaft is pulled and turned, means for transmitting backward resetting motion from said shaft 15 to said numeral wheels individually, a normally retracted locking device moved by said shaft and interacting with said pinion to lock the same against overmovement in the resetting operation, a retracting spring 20 common to said shaft and said locking device, and means for stopping the left-hand numeral wheel at the end of each resetting 25 operation.

103. A register having, in combination, 30 decimal numeral wheels arranged side by side, means for actuating the units wheel in the registering operation, means for transmitting such motion from wheel to wheel including a transfer lug carried by the left-hand 35 side of said units wheel, a transfer pinion interacting with said lug and a spur gear in constant mesh with said pinion, said lug being adapted to contact effectively with said pinion when said units wheel is turned in 40 either direction, an endwise movable and rotatable shaft common to said numeral wheels, a resetting knob by which said shaft is pulled and turned, means for transmitting backward resetting motion from said shaft 45 to said numeral wheels individually, a normally retracted slide interlocking with said pinion to prevent overmovement in the resetting operation, a retracting spring common to said shaft and said slide, and means 50 for stopping the left-hand numeral wheel at the end of each resetting operation.

104. A register having, in combination, 55 decimal numeral wheels arranged side by side, means for actuating the units wheel in the registering operation, means for transmitting such motion from wheel to wheel including a transfer lug carried by the left-hand side of said units wheel, a transfer pinion interacting with said lug and a spur gear 60 in constant mesh with said pinion, said lug being adapted to contact effectively with said pinion when said units wheel is turned in either direction, an endwise movable and rotatable shaft common to said numeral 65 wheels, a resetting knob by which said shaft

is pulled and turned, means for transmitting backward resetting motion from said shaft to said numeral wheels individually, a normally retracted slide parallel with said shaft having a projection which interacts with the teeth of said pinion to lock the same against overmovement in the resetting operation, a retracting spring common to said shaft and said slide, and means for stopping the left-hand numeral wheel at the end of each resetting 75 operation.

105. A register having, in combination, 80 decimal numeral wheels arranged side by side, means for actuating the units wheel in the registering operation, means for transmitting such motion from wheel to wheel including a transfer lug carried by the left-hand side of said units wheel, a transfer pinion interacting with said lug and a spur gear in constant mesh with said pinion, said lug being adapted to contact effectively with said pinion when said units wheel is turned in either direction, an endwise movable and rotatable shaft common to said numeral 85 wheels, a resetting knob by which said shaft is pulled and turned, means for transmitting backward resetting motion from said shaft to said numeral wheels individually, a rod parallel with said shaft, a slide having a guide sleeve embracing said rod and a projection 90 which interacts with the teeth of said pinion to lock the same against overmovement in the resetting operation, a retracting spring common to said shaft and said slide, and means for stopping the left-hand numeral 95 wheel at the end of each resetting operation.

106. A register having, in combination, 100 decimal numeral wheels arranged side by side, means for actuating the units wheel in the registering operation, means for transmitting such motion from wheel to wheel including a transfer lug carried by the left-hand side of said units wheel, a transfer pinion interacting with said lug and a spur gear 105 in constant mesh with said pinion, said lug being adapted to contact effectively with said pinion when said units wheel is turned in either direction, an endwise movable and rotatable shaft common to said numeral 110 wheels, a resetting knob by which said shaft is pulled and turned, means for transmitting backward resetting motion from said shaft to said numeral wheels individually, rods parallel with said shaft one of which supports 115 said pinion, a normally retracted slide having a guide sleeve embracing another of said rods and having a projection which interlocks with the teeth of said pinion during the resetting operation and another projection which interacts with the pinion-supporting 120 rod to prevent said slide from swinging under strain, a retracting spring common to said shaft and slide, and means for stopping the left-hand numeral wheel at the end of the 125 registering operation.

112. In a register, the combination with a set of decimal numeral wheels of means for actuating them and preventing overmovement in the registering operation, including
 5 an actuation transmitter at the left-hand side of said wheels, spur gearing for transmitting rotation to the units wheel and transfer lugs and pinions for transmitting such rotation from wheel to wheel, each transfer lug
 10 being adapted to contact effectively with one of said pinions when the numeral wheel carrying said lug is turned in either direction, means for resetting said wheels or such of them as have been moved in the registering
 15 operation, including an endwise movable and rotatable horizontal shaft on which said wheels as a whole are loose and a knob for pulling and rotating said shaft, rods parallel with said shaft one of which supports said
 20 pinions, a normally retracted slide having a guide sleeve embracing another of said rods and having projections which interlock with the teeth of said pinions during the resetting operation and another projection which in-
 25 teracts with the pinion-supporting rod to prevent said slide from swinging under strains and a bolt moved by said slide and interlocked with said transmitter when said shaft is pulled.

113. In a register, the combination with a set of decimal numeral wheels and right-hand and left-hand frame pieces between which said wheels are mounted of means for actuating said wheels and preventing overmovement in the registering operation including
 30 an actuation transmitter at the left-hand side of said wheels and spur gears, transfer lugs and pinions for transmitting rotation to the units wheel and from wheel to wheel; means for resetting said wheels or such of them as have been moved in the registering operation including an endwise movable and rotatable horizontal shaft mounted in said frame pieces and on
 35 which said wheels as a whole are loose and a knob for pulling and rotating said shaft, a slide movable with said shaft and parallel therewith constructed with projections which interlock with said pinions when said shaft is
 40 pulled and adapt said pinions to contact effectively with the transfer lugs carried by those wheels from which rotation is so transmitted in the registering operation to prevent overmovement of the same in the resetting
 45 operation, a bolt moved by said slide and interlocked with said transmitter when said shaft is pulled, and a retracting spring stretched from said slide to one of said frame pieces.

114. In a double register, the combination with two sets of decimal numeral wheels, arranged side by side, of means for actuating them and preventing overmovement in the registering operation, including actuation
 50 transmitters at the right-hand and left hand

sides of the respective sets, spur gearing for transmitting rotation to the units wheels, and transfer lugs and pinions for transmitting such rotation from wheel to wheel in each set, each transfer lug being adapted to 70 contact effectively with one of said pinions when the numeral wheel carrying such lug is turned in either direction, means for resetting said wheels or such of them as have been moved in the registering operation including an endwise movable and rotatable horizontal shaft on which said wheels of both sets as a whole are loose and a knob for pulling and rotating said shaft, a normally retracted locking device interacting with each 75 pinion when said shaft is pulled and adapting such pinions to contact effectively with the transfer lugs carried by those wheels from which rotation is so transmitted in the registering operation to prevent overmovement of the same in the resetting operation, and a pair of bolts movable with said slide which lock the actuation transmitters respectively during the resetting operation.

115. In a double register, the combination with two sets of decimal numeral wheels, arranged side by side, of means for actuating them and preventing overmovement in the registering operation, including actuation transmitters at the right-hand and left-hand 90 sides of the respective sets, spur gearing for transmitting rotation to the units wheels, and transfer lugs and pinions for transmitting such rotation from wheel to wheel in each set, each transfer lug being adapted to 95 contact effectively with one of said pinions when the numeral wheel carrying such lug is turned in either direction, means for resetting said wheels or such of them as have been moved in the registering operation including an endwise movable and rotatable horizontal shaft on which said wheels of both sets as a whole are loose and a knob for pulling and rotating said shaft, a normally retracted slide which is interlocked with each 100 of said pinions when said shaft is pulled and adapts said pinions to contact effectively with the transfer lugs carried by those wheels from which rotation is so transmitted in the registering operation to prevent overmovement of the same in the resetting operation, and a pair of bolts movable with said slide which lock the actuation transmitters respectively during the resetting operation.

116. In a double register, the combination with two sets of decimal numeral wheels, arranged side by side, of means for actuating them and preventing overmovement in the registering operation including actuation transmitters at the right-hand and left-hand 120 sides of the respective sets, spur gearing for transmitting rotation to the units wheels, and transfer lugs and pinions for transmitting such rotation from wheel to wheel in each set, each transfer lug being adapted to 125 contact effectively with one of said pinions when the numeral wheel carrying such lug is turned in either direction, means for resetting said wheels or such of them as have been moved in the registering operation including an endwise movable and rotatable horizontal shaft on which said wheels of both sets as a whole are loose and a knob for pulling and rotating said shaft, a normally retracted slide which is interlocked with each 130 of said pinions when said shaft is pulled and adapts said pinions to contact effectively with the transfer lugs carried by those wheels from which rotation is so transmitted in the registering operation to prevent overmovement of the same in the resetting operation, and a pair of bolts movable with said slide which lock the actuation transmitters respectively during the resetting operation.

contact effectively with one of said pinions when the numeral wheel carrying such lug is turned in either direction, means for resetting said wheels or such of them as have been moved in the registering operation including an endwise movable and rotatable horizontal shaft on which said wheels of both sets as a whole are loose and a knob for pulling and rotating said shaft, a slide common to all said pinions movable with said shaft and parallel therewith constructed with projections which interlock with the several pinions of both sets when said shaft is pulled and adapt said pinions to contact effectively with the transfer lugs carried by those wheels from which rotation is so transmitted in the registering operation to prevent overmovement of the same in the resetting operation, and a pair of bolts movable with said slide which lock the actuation transmitters respectively during the resetting operation.

117. In a double register, the combination with two sets of decimal numeral wheels, arranged side by side, of means for actuating them and preventing overmovement in the registering operation including actuation transmitters at the right-hand and left hand sides of the respective sets, spur gearing for transmitting rotation to the units wheels, and transfer lugs and pinions for transmitting such rotation from wheel to wheel in each set, each transfer lug being adapted to contact effectively with one of said pinions when the numeral wheel carrying such lug is turned in either direction, means for resetting said wheels or such of them as have been moved in the registering operation including an endwise movable and rotatable horizontal shaft on which said wheels of both sets as a whole are loose and a knob for pulling and rotating said shaft, a rod parallel with said shaft, a slide having a guide sleeve embracing said rod and projections which interlock with the teeth of said pinions when said shaft is pulled and adapt said pinions to contact effectively with the transfer lugs carried by those wheels from which rotation is so transmitted in the registering operation to prevent overmovement of the same in the resetting operation, and a pair of bolts movable with said slide which lock the actuation transmitters respectively during the resetting operation.

118. In a double register, the combination with two sets of decimal numeral wheels, arranged side by side, of means for actuating them and preventing overmovement in the registering operation including actuation transmitters at the right-hand and left-hand sides of the respective sets, spur gearing for transmitting rotation to the units wheels, and transfer lugs and pinions for transmitting such rotation from wheel to wheel in each set, each transfer lug being adapted to contact effectively with one of said pinions

when the numeral wheel carrying such lug is turned in either direction, means for resetting said wheels or such of them as have been moved in the registering operation including an endwise movable and rotatable horizontal shaft on which said wheels of both sets as a whole are loose and a knob for pulling and rotating said shaft, rods parallel with said shaft one of which supports said pinions, a normally retracted slide having a guide sleeve embracing the other rod and having projections which interlock with the teeth of said pinions when said shaft is pulled and adapt said pinions to contact effectively with the transfer lugs carried by those wheels from which rotation is so transmitted in the registering operation to prevent overmovement of the same in the resetting operation and another projection which interacts with the pinion-supporting rod to prevent said slide from swinging under strain, and a pair of bolts movable with said slide which lock the actuation transmitters respectively during the restting operation.

119. In a double register, the combination with two sets of decimal numeral wheels, arranged side by side, and right-hand and left-hand frame pieces between which said wheels are mounted, of means for actuating said wheels and preventing overmovement in the registering operation including actuation transmitters at the right-hand and left-hand sides of the respective sets, spur gearing for transmitting rotation to the units wheels, and transfer lugs and pinions for transmitting such rotation from wheel to wheel in each set, each transfer lug being adapted to contact effectively with one of said pinions when the numeral wheel carrying such lug is turned in either direction, means for resetting said wheels or such of them as have been moved in the registering operation including an endwise movable and rotatable horizontal shaft mounted in said frame pieces and on which said wheels of both sets as a whole are loose and a knob for pulling and rotating said shaft, a slide movable with said shaft and parallel therewith constructed with projections which interlock with said pinions of both sets when said shaft is pulled and adapt said pinions to contact effectively with the transfer lugs carried by those wheels to which rotation is so transmitted in the registering operation to prevent overmovement of the same in the resetting operation, a pair of bolts movable with said slide which lock the actuation transmitters respectively during the resetting operation, and a tensile retracting spring stretched from said slide to one of said frame pieces; substantially as hereinbefore specified.
